UNITED STATES PATENT OFFICE.

HARRY G. WEBSTER, OF CHICAGO, ILLINOIS, ASSIGNOR, BY MESNE ASSIGNMENTS, TO
JAMES R. GARFIELD, TRUSTEE, OF CLEVELAND, OHIO.

TELEPHONE-EXCHANGE SYSTEM.

1,233,940.

Specification of Letters Patent. Patented July 17, 1917.

Application filed March 7, 1913. Serial No. 752,804.

To all whom it may concern:

Be it known that I, HARRY G. WEBSTER, a citizen of the United States, residing at Chicago, in the county of Cook and State of Illinois, have invented a certain new and useful Improvement in Telephone-Exchange Systems, of which the following is a full, clear, concise, and exact description, reference being had to the accompanying drawings, forming a part of this specification.

My invention relates to telephone exchange systems and especially to that class termed "semi-automatic". In systems of this class automatic switching mechanism is employed for extending the connections from the lines of the calling subscribers to the lines of called subscribers. The switching mechanism is preferably controlled by operators who are provided with suitable devices which direct the movement of the switching mechanism.

In an exchange of large capacity wherein, say from one to ten thousand lines or more are connected, I find it desirable to introduce several selections so as to enable any line in the exchange to become connected to any control device. In the present arrangement I use what I term primary, secondary, and tertiary selections. The primary selection is interposed between the calling lines and primary trunks. The secondary selection is interposed between the primary trunks and what are termed secondary trunks. The tertiary selection is interposed between the secondary trunks and the tertiary trunks with which are associated the control devices for directing the automatic switching mechanism.

Instead of using step-by-step switches for effecting connections between the calling lines and operators' positions where the control devices are located, I use a combination of relays. These relays are formed into groups, each group consists of what I term a set of tens and a set of units relays.

The calling lines are formed into groups of one hundred lines each. These lines are served by a group of primary trunks. Each primary trunk has an associated set of tens and units relays so as to effect connections with the calling lines. Each set of relays consists of ten tens relays and ten units relays. Each tens relay contains terminals of ten

lines and it therefore follows that ten tens relays will serve one hundred lines. The operation of the tens and units relays forms cross combinations so as to enable any line of one hundred to become connected to the primary trunk. Where ten per cent. primary trunking is provided it will be possible to care for ten calls originating in the same one hundred lines at the same time. The lines will be multiplied to the contacts of corresponding tens relays associated with each primary trunk. The secondary trunks are each provided with a set of tens and units relays for effecting connection with the primary trunks. These primary trunks are connected to contacts in the tens relays of the secondary set in the same manner in which the lines are connected to contacts of the tens relays in the primary set. The operation of the tens and units relays in the secondary set forms the proper cross combinations so as to enable any one of a group of primary trunks to become connected to the secondary trunk.

The tertiary trunks are each provided with a set of tens and units relays for effecting connection with the secondary trunks. The secondary trunks are connected to contacts of the tens relays of the tertiary set. The operation of the tens and units relays forms cross combinations so as to enable any one of a group of secondary trunks to become connected to the same tertiary trunk or control device.

My invention also relates to the manner in which the various groups of relays are controlled so as to prevent interference in case of simultaneous calls and also the manner in which the various primary, secondary, and tertiary trunks are placed in service. In order to prevent interference each group of lines and each group of secondary and tertiary trunks is provided with a group of control relays which determine the sequence in which the tens and units relays of the various sets are to be operated. Further objects of my invention relate to the manner in which the circuits and contacts of these control relays are guarded or protected. With each set of control relays a step-by-step circulator or guard switch is employed. These guarding switches associated with the primary, secondary, and tertiary control relays change the order of precedence as be-

tween groups of calling lines and trunks to secure uniformity of selection and to prevent tying up entire groups of lines or trunks.

5 Some novel features in the system in addition to the foregoing are as follows:—

The provision of suitable alarm signals which are operated in case of a failure to effect proper connections between groups of trunks.

10 The manner in which a delayed release is secured so as to prevent the accidental release of a calling line.

The manner in which the test contact of a 15 two-wire trunk selector is rendered busy until the trunk selector switch restores.

The manner in which control is extended to the two-wire trunk from the connector.

20 The provision of a guarding switch arranged to step after a delayed period to control the starting circuit of the tertiary trunks or control devices.

The manner in which the connection from a secondary trunk to a tertiary trunk is controlled over three conductors.

25 Various other novel features will be pointed out in the detailed description to follow.

30 My invention is illustrated in the accompanying drawings, wherein:

Figure 1 shows a group of subscribers' line circuits and a series of tens and units primary relays for connecting the lines to primary trunks.

35 Fig. 2 shows a primary trunk with its associated first selector switch.

Fig. 3 shows a second selector switch.

Fig. 3^a shows a two wire trunk for use between exchanges.

40 Fig. 4 shows a connector circuit with its associated switch arranged for five party selective ringing.

Fig. 4^a shows a connector circuit with its associated switch arranged for ten party selective ringing.

45 Fig. 4^b shows a private branch exchange connector arranged for five party selective ringing.

Fig. 4^c shows a private branch exchange 50 connector arranged for ten party selective ringing.

Fig. 5 is a duplication of Fig. 1 and represents the called subscribers' line equipments.

55 Fig. 6 shows a set of relays and switches for controlling the primary relays and primary trunks.

Fig. 7 shows a set of relays and switches 60 for controlling a set of secondary tens and units relays.

Fig. 8 shows a set of tens and units relays for connecting the primary trunk to the secondary trunk.

65 Fig. 9 shows the circuits of a secondary trunk.

Fig. 10 shows the control circuits for the tertiary set of tens and units relays.

Fig. 11 shows a tertiary set of tens and units relays for connecting the secondary trunk to the tertiary trunk with which is 70 associated an operator's key-board and sending device.

Fig. 12 shows a tertiary trunk for controlling the operation of the key-board and sending device.

75 Fig. 13 shows an operator's key-board and sending device.

Fig. 14 shows the manner in which the primary circulator or emergency switch guards the series contacts of the primary 80 control relays and primary trunks.

Fig. 15 shows the manner in which the secondary control circuit is guarded by the secondary circulator or emergency switch.

Fig. 16 shows the manner in which the 85 tertiary control circuit is guarded by the tertiary circulator or emergency switch.

Fig. 17 shows the arrangement of the various figures when a subscriber calls for another subscriber in the same exchange.

90 Fig. 18 shows the arrangement of the various figures when a subscriber calls for a private branch exchange.

Fig. 19 shows the arrangement of the various figures when a subscriber in one exchange 95 calls for a subscriber in another exchange.

Referring to Fig. 1 I have shown five subscribers' line circuits, each line being provided with an individual line and cut-off 100 relay.

I have only shown one sub station at A equipped with apparatus usual in common battery systems.

In the present arrangement, I have shown 105 the five subscribers' lines numbered 21, 22, 23, 31 and 32, so as to show how various combinations of lines can become connected to primary trunks through the same set of relays by having the relays themselves in 110 acting perform certain cross combinations.

For each group of one hundred lines, where ten per cent. trunking is used, there will be ten tens relays and ten units relays for each primary trunk. The tens relays 115 are numbered from 1 to 10, while the units relays are numbered from 11 to 20.

Each one of the tens relays of a set contain the terminals of ten lines so it therefore follows that ten relays will care for 120 one hundred lines. For each additional primary trunk, there will be another set of tens and units relays and in case ten primary trunks are provided, the subscribers' lines will be multiplied ten times.

125 Corresponding contacts in the tens relays of a certain set are multiplied and connected to contacts in the units relays of the same set in the following manner: the multiple of number one set of contacts of the tens re- 130

lays are connected to contacts in the first units relay while the multiple contacts of the second set of contacts in the tens relays are connected to the contacts in the second units relay.

When the first tens relay and the first units relay of one set are energized, it naturally follows that the line connected to the first set of contacts in the first tens relay is connected to contacts in the first units relay.

The contacts in the units relays which engage contacts leading to the multiple connections in the tens relays are connected directly to wires leading to a primary trunk. These primary trunk wires are multiplied to the contacts in each units relay of its set. When the first tens and the first units relays are energized, it therefore follows that the line connected to the first set of contacts in the first tens relay is connected to a primary trunk.

If the subscriber whose line is number 31 should originate a call, the action of his line relay through the control circuit would energize tens relay 2 and units relay 11, thereby connecting his line to the primary trunk.

Subscriber 32 originating a call would cause tens relay 2 to become energized and the units relay 12, thereby connecting his line to the primary trunk.

It is only possible for one tens and one units relay in a certain set to become energized at the same time. When a tens and a units relay of a set are energized, the rest of the relays of the set are prevented from operating and the control circuit is shifted to the next set of tens and units relays to place them in operative condition.

Referring to Fig. 6, a group of relays for controlling the action of the tens and units relays in Fig. 1 is provided to prevent interference in case of simultaneous calls from the same group of line relays. If some provision was not made, then in case of such calls, more than one tens and one units relay could become energized in the same primary set.

Relay 382, (Fig. 1), is individual to a primary trunk, while the rest of the relays shown in this, Fig. 6, are common to a group of one hundred lines. There will be ten relays 321 to 330, ten relays 331 to 340 and ten relays 341 to 350. Each of the relays 321 to 330 is individual to a group of ten line relays, while a set of relays 331 to 340 is controlled by the set of relays 321 to 330. Relay 321 controls relay 331, and relay 322 controls relay 332, etc. Each relay in the set 331 to 340 is provided with eleven sets of contacts in order to enable a tens relay in the primary set to be operated, and also to allow any one of the ten units relays in the primary set to become operated. The contacts of relays 321 to 330 which operate their respective relays 331 to 340 are ar-

ranged in a series relation so that only one of the relays 331 to 340 can be operated at the same time.

The tens starting wire belonging to a group of ten line relays is multiplied while the units wire of each line relay is individual and connected in groups in their respective control relays 331, 332, 333, etc. as the case may be.

For each group of ten line relays, the tens wire will be multiplied, enabling any relay of the ten when operated to close the circuit of its control relay in the set 321 to 330.

These control relays are operated through the normally closed contacts of a master relay 358 associated with the group of relays 321 to 330. As soon as any relay 321 to 330 of the group is operated the circuit of the master relay is closed. This latter relay in operating opens or disconnects all of the tens starting wires from the group of control relays.

A master relay is also provided for the set of relays 341 to 350. These latter relays are operated by the action of the line relays 331 to 340 when the relays 331 to 340 are operated.

The operation of either one of the relays 341 to 350 closes the circuit of the master relay 359 which in acting opens the units starting wires leading to the group of control relays 341 to 350.

The controlling contacts for operating the proper units relay in the primary set, when relay 382 is operated, are in a series relation so that the action of only one relay is effective.

By the foregoing arrangement only one of the relays in the set 331 to 340, each representing a group of ten lines can become energized at the same time. The energized relay connects the units wires of its group of line relays to the windings of the unit control relays of the set 341 to 350 through contacts of relay 359 and as only one of these former relays when operated is effective, it therefore follows that only one tens and one units relay of the primary set can be operated at the same time, no matter how many line relays are energized.

Switch K is a circulator or emergency switch which under normal conditions takes one step at each call. This switch is provided with three sets of bank contacts and wipers. The wiper and contacts of the portion 360 serves to change the location of the ground connection in relation to the series contacts of the control relays 321 to 330. At each step of the switch K the ground is shifted from one contact to the one following it. The wiper and contacts of the portion 361 serves to change the location of the ground connection in relation to the series contacts of the control relays 341 to 350. The wiper and contacts of the portion 362 serves to change the order in which the

primary trunks are placed in service. In case of any undue delay in a calling line becoming connected to a primary trunk the switch K will continue to step and change the location of the ground in relation to the series contacts and also place another primary trunk in operative condition.

16 The functions of this switch K will be fully described in detail later when describing the operation of the system.

17 Referring to Fig. 2, a primary trunk is shown terminating in a first selector switch D. Relay 111 and the retardation coil 112 are connected respectively to the tip and 15 sleeve sides of the trunk. The relay 111 has one terminal connected to ground while the retardation coil 112 has one terminal connected to the free side of the battery to supply talking current to the calling subscriber.

20 Relay 110 is placed in series with the cut-off relay of the calling line after the tens and units relays of the primary set are operated. Relay 121 corresponds to the line relay inasmuch as it primarily selects the proper 25 tens and units relays of the secondary trunk so as to form the combination of the calling primary trunk with which it is associated.

26 Relay 114 is operated after the secondary selection has been effected and the primary 30 trunk connected to an idle key-set. The action of relay 114 at this time closes the circuit of the relay 113, which in turn opens the starting wires leading to the tens and units relay of the secondary set. Relay 113

35 after being operated, remains locked to ground through the back contact of relay 115. This latter relay is not operated until after the switch D rotates and the calling subscriber hangs up his receiver, thereby 40 deenergizing the tip relay 111. The operation of the relay 115 closes the circuit of the release relay 125 which in time causes the operation of the release magnet 149, thereby restoring the switch D to its normal 45 position. Relay 119 is the test relay of the first selector switch D and is energized by a test impulse from the sending device and remains energized while the test wiper 142 is passing over busy or grounded contacts.

50 The operation of relay 119 completes the circuit of relay 117, which in operating, severs the trunk conductors so as to prevent interference while the wipers of the switch D are passing over busy contacts.

55 Relay 109 is a slow acting relay energized by the action of the relay 111. The action of the former relay serves to prevent disconnection in case the calling subscriber should accidentally move his receiver hook.

60 While the relay 109 is energized, the release circuit of the switch D is disabled. This release circuit can only become effective when relay 109 is in its normal position and after the switch D has rotated and stepped vertically. After the switch steps in a ver-

tical direction and the wipers 142 and 143 engage test contacts leading to the second selector switch, then these two wipers become short circuited and complete the circuit of relay 115. The operation of relay 115 completes the circuit of relay 125 which in turn closes the circuit of the release magnet 149.

65 It will be noted that the two wipers 142 and 143 are separated; wiper 142 serving as a test wiper, while the other serves to control the release. The relay 125 when energized opens the locking circuit of the tens and units relays of the primary set, thereby freeing the calling line from the primary trunk. After a subscriber's line once becomes connected to a primary trunk, it can only be freed therefrom when the wipers of the first selector switch engage test contacts, thereby short circuiting the wipers 142 and 143.

70 Relay 116 is a vibrating relay and used in conjunction with the vertical magnet 118 causing the switch D to automatically step after the test impulse has been delivered. 75 This relay also connects ground to the locking contact of the test relay 119, so that when this latter relay is energized, it cannot become deenergized until the test wiper 142 engages an idle contact and relay 116 is 80 energized. Relay 116 becomes energized however just as soon as the vertical magnet 118 completes its stroke, and at this time the wiper 142 engages a test contact.

85 Relay 122 is the rotary stepping relay placed in series with the control relay of the sending device. The operation of the former relay closes the circuit of the rotary magnet 120 of the switch D. The magnet in operating closes the circuit of relay 123 90 thereby disconnecting relay 122 and consequently breaking the circuit of the control relay of the sending device.

95 Referring to Fig. 3, the second selector switch is shown at E. 162 is the rotary stepping relay which is placed in series with the control relay of the sending device. The operation of relay 162 causes the switch E to step in a rotary direction. 167 is the test relay and responds to the test impulse from the sending device and when operated closes the circuit of the vertical magnet 165, causing the switch E to step vertically until an idle connector switch is found. Relay 164 105 is energized by the action of the relay 167 which in operating, severs the trunk connectors so as to prevent interference. 161 is the vibrating relay serving to open and close the circuit of the vertical magnet 165 and also to insure a full stroke of the vertical magnet. This relay maintains the circuit of the relay 167 closed until after its own circuit is closed, which happens when the vertical magnet 165 completes its stroke.

110 Relay 163 serves to control the release cir-

115

cuit and also to render the test contacts in the first selector switch busy, while the switch E is restoring. This relay is operated by the first action of the relay 162 and in operating, locks itself to ground over the test wire 152. The circuit of the release magnet 168 is closed when relay 167 is deenergized and relay 164 is energized. The foregoing combination takes place when ground is removed from the test wire 152, relay 163 deenergized and the switch E in an off-normal condition. When the switch is in such a condition, the rotary cam springs 151 are closed and ground connected to the winding of relay 164. This relay will remain energized until the switch reaches its normal position. At the first vertical step of the switch E the cam springs 158 are operated, thereby disconnecting relays 167 and 162 respectively from the trunk conductors.

Referring to Fig. 3^a a two-wire trunk is shown. That portion to the right of the dotted lines is located at a distant exchange while that shown to the left is located in the originating exchange. Relay 810 is a quick acting relay while relay 811 is a sluggish relay. These two relays are operated when the first selector switch, Fig. 2, starts to restore. The effect of these two relays in operating is to place a momentary ground on the trunk wires leading to the distant exchange in order to release the switch E'. Relay 811 being a slow acting relay falls back and disconnects ground from both sides of the trunk while relay 810 is energized. Relay 810 will remain energized until the switch E' reaches its normal position. While the switch E' is in an off normal position and relay 810 energized, ground is connected to the test contact 832 so as to prevent other first selector switches selecting this particular trunk. The switch E' is provided with two sets of wipers, 863, 864, and 865, 866. The former wipers engage contacts over which conversation is carried on, while the latter wipers engage contacts over which the control and testing is exercised. Relay 812 is the stepping relay for the switch E' and when placed in series with the control relay of the sending device over the tip side of the trunk, causes the switch E' to step in a rotary direction and bring its wipers in line with the proper row of contacts. As soon as this switch rotates the cam springs 860 are closed. The operation of relay 812 will close the circuit of relay 800 which in turn will close the circuit of relay 802. The operation of the relay 802 opens one path from the tip side of the trunk 830 to the winding of the relay 812. After relay 802 is operated, its circuit is maintained to ground through the contacts of relay 813. Relay 823 is operated at each stroke of the rotary magnet 808, thereby

breaking the series circuit between relay 812 and the control relay of the sending device.

As soon as the switch E' rotates and closes the contacts 860, relay 820 becomes energized and connects relay 813 to the sleeve side of the trunk 831 through the contacts of relays 819 and 821. The connecting of relay 813 to the sleeve side of the trunk places it in series with the control relay of the sending device. The operation of the relay 813 closes the circuit of the relay 803 which in turn closes the circuit of the relay 821. The operation of relay 813 also completes the circuit of the test relay 814 through the contacts of relay 822 and the vertical cam springs 861 of the switch E' and at the same time opens the circuit of relay 802 thereby closing a path from the tip side of the trunk to the winding of the relay 812. The operation of relay 814 completes the circuit of the vertical magnet 809 from ground through the back contacts of relay 817. As soon as magnet 809 completes its stroke however it closes the circuit of the relay 817 thereby removing ground from its own winding. The operation of the relay 817 also removes ground from the locking contact of relay 814 and should the wiper 865 engage a contact free from ground at this period, relay 814 would immediately fall back and prevent further stepping of the switch E'. If however a grounded contact is engaged, the circuit of relay 814 will be maintained closed and the switch E' will step vertically until an idle contact is reached. The operation of relay 814 completes the circuit of relay 816. This latter relay in turn completes the circuit of relay 815. Relay 815 in operating severs the tip and sleeve conductors while the wipers 863 and 864 are passing over busy contacts. The operation of relay 816 also completes the circuit of relay 819 thereby disconnecting the winding of the relay 812 from the contact of relay 823. It will be noted that the relay 812 is now only connected to the tip conductor 830 through the back contacts of relay 802. The circuit of relay 819 will be maintained locked through the back contacts of relay 818, front contacts of relay 820 and back contacts of relay 822. The action of relay 819 short circuits the condensers 866 and 867 so that the control relay of the sending device can be placed in series with the stepping relays of the connector switch. After the switch E' picks out an idle connector then relays 814, 816 and 815 fall back and the connector can then be controlled by the sending device.

When the control relay of the sending device is placed in series with the stepping relay of the connector switch relay 812 is operated and in acting closes the circuit of relay 800 which in turn completes the circuit of the relay 802. The action of this latter

relay at once disconnects relay 812 from the tip conductor 830. The action of relay 812 unlocks relay 821 which again connects relay 813 to the sleeve conductor 831. When the control relay of the sending device is placed in series with the stepping relay of the connector over the sleeve side of the trunk, relay 813 is again operated but at once closes the circuit of the relay 803 which in turn completes the circuit of relay 821 which at once removes relay 813 from the sleeve conductor. The operation of relay 813 unlocks relay 802 again connecting the winding of the relay 812 to the tip conductor. From the foregoing it will be seen that after stepping relays 812 and 813 operate the switch E' they are only momentarily affected while the connector is being operated and no effect is caused by this momentary action. In fact as soon as these stepping relays operate once while the connector is being operated, they at once operate other relays which in turn disable the stepping relays themselves. When the final test impulse is sent to the connector in order to determine whether the called for line is busy, relay 272 (Fig. 4), responds and besides connecting the relay 274 to the wiper 266, it also connects ground to wire 207 through the cam springs 296 of the switch G. This ground operates relay 818, (Fig. 3^a) as the wiper 266 engages the contact to which the wire 207 is connected. The operation of the relay 818 disconnects relay 819, thereby removing the short circuits from the condensers 866 and 867. The condensers are inserted in the talking circuit after the connection is established to prevent battery supply in the connector from flowing back over the tip and sleeve conductors extending to the originating exchange.

The release of the selector E' is controlled by the calling subscriber. In hanging up his receiver, he causes the first selector D to restore. In restoring the selector, ground is placed on wiper 143 engaging the contact to which relay 811 is connected. This ground is of only a momentary nature and is removed as soon as the wiper 143 leaves the contact. Relay 811 however becomes energized and operates relay 810 from battery through the high wound resistance coil 834. The operation of relay 810 connects ground through the front contact of relay 811 to the tip conductor and ground through its own winding and locking contact to the sleeve conductor. This relay also connects ground to the wire leading to the test contacts 832 of the first selector switch. Ground being placed on the tip side of the trunk momentarily operates relay 812 and ground placed on the sleeve side of the trunk operates relay 813. The relays 810 and 813 will remain energized in series until the circuit of relay 813 is broken by relay 820 falling

back. This latter relay can only fall back however when the switch E' restores and opens the cam springs 860. While relay 812 and relay 813 are operating at the same time, the former only momentarily, the circuit of relay 822 is closed and in turn closes the circuit of release magnet 872. The operation of magnet 872 causes the switch E' to restore.

From the foregoing description it will be seen that the trunk selector cannot be selected by a first selector at the originating end until the switch at the distant point has restored to its normal position.

Referring to Fig. 4, the connector switch G is provided with two sets of wipers, 297 and 266. The former wipers serve to engage the tip and sleeve contacts of the called line over which the conversation is carried on. Wiper 266 engages a contact leading to the cut off relay of the called line and also serves as the test wiper.

The connector switch G has associated with it a selecting switch F which serves to pick out ringing current of the proper character and also controls the release of the connector switch G. The portion J of the switch F serves to pick out the proper ringing current; the portion I serves to restore the switch F to its normal position at the proper time; while the portion H serves to release the switch G. The wipers of the switch F rotate in the direction indicated by the arrows. The stepping of this switch is controlled by the magnet 281 which operates a number of times corresponding to the button pressed in the strip 711 (Fig. 13).

The two relays 287 and 288, the former being a slow acting relay control the restoration of the switch F. These two relays when acting cause a vibrating effect in the circuit of magnet 281, causing it to stop the wipers of the switch F until the wiper of the portion I reaches its normal position. 270 is the stepping relay which is placed in series with the control relay of the sending device over the tip side of the trunk. The operating of relay 270 closes the circuit of the stepping magnet 281 causing the wipers of the switch F to rotate. Relay 271 is operated by the magnet 281 and also by either of the magnets 289 or 290 when they complete their stroke. The operating of relay 271 disconnects relay 270 from the tip side of the trunk, thereby causing the control relay of the sending device to fall back. 272 is the stepping relay which is placed in series with the control relay of the sending device over the sleeve side of the trunk. The operating of the relay 272 closes the circuit of the rotary magnet 290 of the switch G causing it to rotate. 275 is a control relay energized by the action of relay 270 and deenergized by the action of relay 272. Relay 291 is operated when relay 272 acts and serves to dis-

connect the stepping magnet 281 and in its place connect the vertical magnet 289. One terminal of the retardation coil 280 is connected to the free side of battery, the other terminal being connected to the tip side of the trunk. One terminal of the relay 277 is connected to the grounded side of the battery, through the back contact of relay 270, the other terminal being connected to the sleeve side of the trunk and with the retardation coil 280 are in the circuit of the talking current to the called subscriber. Relay 276 is placed in series with the cut-off relay of the called line when the wipers of the switch G engage contacts of the line. The operation of relay 276 closes the circuit of relay 278 and the operation of this latter relay places the auxiliary ringing switch M in operative condition.

This switch M is provided with a stepping magnet 283 which controls the three disks 210, 215 and 220. These three disks are mounted on the same shaft or spindle and operate at the same time. At the first action of the magnet 283 the cam 220 breaks the contact of springs 219 and 221 and closes contacts 221 and 222. When this first step is taken, disk 210 closes contacts 211 and 212 and breaks contacts 212 and 213. The closing of the contacts 211 and 212 connects generator current of the character selected by the switch F to the tip side of the trunk. At the first stepping of the switch M, the disk 215 in moving breaks contacts 214 and 216 but closes contacts 216 and 217. Contact 217 is connected to the grounded resistance coil 218. This resistance coil is connected to the sleeve side of the trunk and forms a return path for the generator current.

The switch M will continue to step under the influence of the group of relays 282, 298 and 284 and cause the disks to rotate. Immediately following the ringing period, the cam 210 closes its contact springs 212 and 213 before the cam 215 closes its contact springs 216 and 214. This arrangement places battery through the retardation coil 280 to the tip side of the line so as to provide a line discharge. Discharging the line in this manner prevents a momentary action or flipping of relay 277. If the called subscriber removes his receiver when the disks are in the position as shown in the drawing, relay 277 is operated and prevents any further action of the switch M, as relay 291, through which the ringing control circuit passes, becomes deenergized.

Relay 279 is operated when the switch is stepping in a vertical direction and also when the switch is restoring so as to prevent interference while the wipers are passing over busy contacts. 285 is the release relay which has its circuit closed through the portion H of the switch F when the wiper reaches contact 299. 274 is a busy test relay

and is only energized in case the called for line is busy and in such an event energizes relay 279 thus opening the line and test wipers until released and connects a suitable busy tone signal to the calling subscriber.

Referring to Fig. 4^a the connector switch G' is operated in the same manner as switch G, Fig. 4.

The selective ringing switch however is arranged for ten party selective ringing so that five parties can be rung selectively from the tip side of the line to ground, while five other parties on the same line can be rung selectively from the sleeve side of the line to ground. Portion J' of the switch F' is provided with two segments so that for the first five steps of the switch F', generator current will be connected to the tip side of the line. The next five steps of the switch F' will connect generator current to the sleeve side of the line. One segment of the portion J' is connected to a contact of the auxiliary switch M' while the other segment is connected to a separate contact in the switch M'. The contacts in the auxiliary switch M' are so arranged that the wires from the two segments are connected respectively to the tip and sleeve sides of the line at the same time. The portion H' of the switch F' at the first five steps connects ground to the sleeve contact of the switch M' and at the next five steps, ground is connected to the tip contact of the switch M'. With this arrangement, generator current is connected to the tip contact and ground is connected to the sleeve contact when the switch F' takes from one to five steps. When the switch however takes from six to ten steps, generator current is connected to the sleeve contact and ground to the tip contact of the switch M'.

The only difference in the operation of the ten party connector over that of the five party connector is that when one to five impulses are transmitted, generator current is connected to the tip side of the line and when six to ten impulses are transmitted, generator current is connected to the sleeve side of the line. The switch M' is provided with an extra disk 900, and disk 920, which corresponds to the disk 220, (Fig. 4), operates an extra relay 998. The object of this relay is to short circuit the tip and sleeve sides of the line just after the ringing period in order to discharge the line to prevent the momentary action of relay 977. After the ringing period and after relay 998 falls back, the calling subscriber, upon removing his receiver, causes the relay 977 to become energized and so disable the ringing circuit.

Referring to Fig. 4^b, the private branch exchange connector is operated in the same manner as the regular connector, Fig. 4. The connector in Fig. 4^b differs from the

regular connector only in the manner of testing. The test relay 1074 which corresponds to the regular test relay 274, (Fig. 4), instead of energizing relay 1079 when energized, simply causes the switch G^2 to step vertically until an idle trunk is found. The test relay 1074 is connected to the test wiper 1066 when the test impulse is delivered and in case the first trunk or line engaged is found busy, the test relay will become energized and its locking circuit maintained through the test contact engaged by the wiper 1066. The operation of the test relay 1074 connects ground to the tip side 15 of the trunk 1050 and at this time relay 1091 is energized. The ground placed on the tip conductor by the test relay causes relay 1070 to become energized and operate the vertical magnet of the switch G^2 through 20 the upper contacts of relay 1091. At each stroke of the vertical magnet 1089 the relay 1071 is operated thereby opening the circuit of the stepping relay 1070. This vibrating effect will continue and the switch G^2 will 25 step vertically until the wiper 1066 engages an idle trunk or line. As soon as such a line is found, relay 1074 falls back and disconnects ground from the tip conductor thereby preventing further action of relay 1070. 30 Relay 1008 is connected to the wiper 1009. This wiper engages contacts associated with the various lines or trunks. These contacts associated with the trunks are simply blank and under normal conditions relay 1008 is 35 not operated. If however all of the trunks leading to a particular exchange are busy, the switch G^2 will continue to step and engage an extra set of contacts immediately above the contacts to which the last trunk 40 is connected. The extra contact which the wiper 1009 then engages, is permanently grounded and the effect of this ground causes the operation of relay 1008. The extra contact which the wiper 1066 engages 45 is a blank contact and therefore relay 1074 falls back, removing the ground from the tip side of the trunk. The operation of relay 1008 connects a suitable busy tone test to the trunk notifying the calling subscriber 50 that all of the trunks are engaged.

During the operation of the test relay 1074 the circuit of relay 1079 is closed. This latter relay severs the tip and sleeve conductors and prevents interference while the 55 wipers 1090 are passing over busy trunks or lines.

The only difference between the private branch exchange connector and the regular connector is that the test relay when operated causes the automatic stepping of the switch G^2 and that an extra wiper 1009 and extra relay 1008 are provided. The balance 60 of the circuits and apparatus is identical with that of the regular connector. 1070 and 1072 are stepping relays and 1071 is the

vibrating relay for controlling them. 1091 is the shifting relay used for disconnecting the stepping magnet 1081 and in its place connecting the vertical magnet 1089. The coil 1080 and relay 1077 being connected respectively to the free and grounded side of the battery, furnish a path for talking current to the called subscriber. 1085 is the release relay while 1078 is the relay for controlling the local circuit of the auxiliary 75 switch magnet 1083. The disks 1010, 1015 and 1020 correspond to disks 210, 215 and 220 of Fig. 4. 1087 and 1088 are the two relays for controlling the restoring of switch F^2 . A group of relays 1082, 1098 and 1084 80 are used for causing the stepping of the magnet 1083. These two groups of relays can be common to a plurality of private branch exchange connectors. Relays 1098, 1084 and 1087 are sluggish in their action 85 and relay 1074 is of the same type.

Referring to Fig. 4^c, a ten party private branch exchange connector is shown. This connector acts in the same manner as the one previously described in Fig. 4^b. The 90 only difference between the ten party connector and the five party connector is in the ringing arrangement. The ringing arrangement in Fig. 4^c is identical with that of the regular ten party connector shown in Fig. 95 4^a. It will not be necessary to describe this circuit in detail at this time for in tracing a connection, we will describe the operation of the ten party connector shown in Fig. 4^c and the operation of the five party private 100 branch exchange connector shown in Fig. 4^b. In describing in detail the operation of Figs. 4^a and 4^b all the points will be covered relating to Figs. 4 and 4^c.

Referring to Fig. 5 the circuits shown on 105 this sheet are identical with those of Fig. 1 and need not be described.

Referring to Fig. 7 a set of relays and a circulator switch are shown for controlling the tens and units relays of the secondary 110 sets. These latter relays are controlled by the group of relays, Fig. 7, in the same manner in which the primary relays, Fig. 1, are controlled by the group of relays, Fig. 6.

Relay 419, Fig. 7, is individual to a set 115 of tens and units relays, Fig. 8, which are associated with a secondary trunk shown in Fig. 9. The rest of relays in Fig. 7 are common to a group of 100 primary trunks, served by a group of secondary trunks, one 120 of which is shown in Fig. 9. This group of relays, Fig. 7, controls the calls from 100 primary trunks in the same manner as the group of relays, Fig. 6, controls the calls from 100 lines.

Referring now to Fig. 7, each group of 100 primary trunks will have ten relays, 421, 422, 423, etc., ten relays 431, 432, 433, etc., and ten relays 441, 442, 443, etc. The first set of relays mentioned will have a 130

common control or master relay, 471. This master relay, when energized, then prevents any relay of its set becoming operated. The third set of relays mentioned are controlled by a master relay 472; its function being the same as that of relay 471. The relays of the second set mentioned are each provided with eleven sets of normally open contacts. One of these contacts, which is permanently grounded, serves to control the tens relay of a secondary set, such as shown in Fig. 8. The remaining ten contacts of each relay are multiplied and serve to control the units relays of a secondary set such as shown in Fig. 8. The contacts of the set of relays 421, 422, 423, etc., which control relays 431, 432, 433, etc., are in a series relation so as to prevent interference in case of simultaneous calls. In case of such calls and should more than one relay of the set 421, 422, 423, etc., become operated, only one will be effective. The contacts of the set 441, 442, 443, etc., which control the units relays of the secondary set, Fig. 8, are in a series relation so that in case of simultaneous calls the action of one only is effective. Each of the relays of the set 401, 402, 403, etc., is individual to a secondary trunk, Fig. 9, and operated when such a trunk is selected.

30 A circulating or emergency switch T is provided for guarding the series control contacts of the set of relays 421, 422, 423, etc., and of set 441, 442, 443, etc. This switch also serves to change the order in which the secondary trunks, Fig. 9, are placed in service. Relays 481 and 482 are alarm or off-normal signals provided in case of any undue delay in effecting connections. The manner in which these signals are controlled will be described later.

Referring to Fig. 8, a set of tens and units secondary relays are shown. Relays 521, 522, 523, etc., are the tens relays. There will be ten of these relays associated with the secondary trunk, Fig. 9. Relays 531, 532, 533, etc., are the units relays and there will be ten of these relays associated with this secondary trunk. These relays correspond to the tens and units relays in Fig. 1. Instead of a group of lines being connected to contacts in the tens relays as in the first instance, there will be a group of primary trunks connected. Each full group of secondary relays will contain the terminals for 100 primary trunks, thus allowing 100 primary trunks or 1000 lines to become connected to one secondary trunk, Fig. 9.

Each group of 100 primary trunks however can be served by a certain number of secondary trunks such as shown in Fig. 9, in the same manner that 100 lines are served by a group of primary trunks. The wires from the primary trunks will be multiplied into each group of tens relays of the secondary set in the same manner as the lines

are multiplied into different groups of tens relays of the primary set.

Referring to Fig. 9, relay 552 is operated when the secondary trunk is connected to the primary trunk through the tens and units relays, Fig. 8. Relay 552 controls the locking circuits of the tens and units relays when operated and also causes the operation of relay 556. The operation of relay 556 completes the circuit of relay 555. This latter relay is the shifting relay and when operated connects the starting wire to the next trunk of the set and also opens the circuit of relay 552. The operation of relay 556 connects ground to the third wire 545 through the back contacts of relays 553 and 600.

There are only three wires 513, 514, and 545 leading from the secondary trunk to the tertiary set of tens and units relays, Fig. 85 11. The control for selecting the proper tens and units relays of the tertiary set is exercised over the third conductor 545. When the tertiary selection is complete, relay 551 is operated by battery and ground 90 being placed on the tip and sleeve conductors at the tertiary end through the winding of relays 662 and 668, Fig. 12. The operation of relay 551 completes the circuit of relay 553 which is a slow acting relay. 95 The operation of relay 553 opens one path of the third conductor but closes a second path and also operates relay 554 and the operation of this latter relay maintains the circuit of relay 555 closed after relay 556 100 subsequently falls back. Relay 554 also connects ground to the locking contacts of the tens and units relays, Fig. 8, after relay 552 falls back. The locking circuits of the tens and units relays, Fig. 8, are also controlled 105 by relay 556. When the starting button 705, Fig. 13, is pressed in order to establish a connection, relay 550 is operated over the third conductor through the contacts of relay 553. The operation of relay 550 opens 110 the circuit through relay 551. Relay 551 opens the circuit of the slow acting relay 553. Before this relay can open its contacts the operation of relay 550 places relay 600 in series with relay 114, Fig. 2. 115 While the connection is being established, the following relays in the secondary trunk are energized: 600, 550, 554 and 555. The operation of relay 554 at this time maintains ground on the locking contacts of tens and 120 units relays, Fig. 8. After the connection is established, the third conductor is opened at the key set or tertiary end and relay 550 falls back, opening the circuit of relay 600, which in turn opens the circuit of relay 554. The 125 latter relay falling back, opens the circuit of relay 555, also the locking circuit of the tens and units relays, Fig. 8, and all parts of the secondary trunk are restored to their normal position.

Referring to Fig. 10, the control circuits for the tertiary set of tens and units relays is similar to the control circuits shown in Figs. 6 and 7. Relays 585, 586 and 587 are individual to a secondary trunk, Fig. 9, but can be located at a distant point. Relay 585 corresponds to and performs the same functions as a line relay. In acting this relay closes the tens and units starting

wires so as to operate the proper tens and units relays of the tertiary set, Fig. 11, the combination of which forms the number of the calling secondary trunk. Relays 586 and 587 perform the same functions as the cut-off relay of a calling line and serve to disconnect relay 585 at the proper time.

The rest of the relays, Fig. 10, as well as the emergency switch L, are common to a group of 100 secondary trunks as in Fig. 9. Relays of the set 451, 452, 453, etc., are responsive to the tens starting wires of the secondary trunks. This set of relays is controlled by a master relay 581. The operation of any relay of the set will close the circuit of the master relay 581 which in operating opens the tens starting wires so as to prevent interference. There are ten relays in this first set to form a complete group, each of which is common to a group of ten trunks. The set of relays 561, 562, 563, etc., are controlled by their respective relays in the first set and when energized, connect the individual units starting wires to the third set of relays 571, 572, 573, etc. There will be 11 contacts in each of the relays 561, 562, 563, etc. The grounded contact is for operating the proper tens relay of the set shown in Fig. 11, while the other ten contacts are connected to the units starting wires so as to operate any one of the relays of the set 571, 572, 573, etc. The operation of one of these latter relays completes the circuit of the proper units relay Fig. 11.

The contacts of the first set of relays which control relays 561, 562, 563, etc., are in a series relation while the contacts of the set 571, 572, 573, etc., which control the units relays, Fig. 11, are in a series relation. These two sets of series contacts are controlled by the circulator switch L so that in case of a failure of operation due to an open contact in the series, the switch L will step until the open contact is passed and connect ground beyond the open contact.

The detail operation of the switch L and of the various relays will be explained later.

Fig. 10 does not show a complete set of control relays. In order to complete such a set, there would be ten relays, 451, 452, 453, etc., ten relays 561, 562, 563, etc., and ten relays 571, 572, 573, etc.

Referring to Fig. 11, a set of tertiary

tens and units relays are shown. There will be ten tens relays 601, 602, 603, etc., and ten units relays 611, 612, 613, etc., associated with each tertiary trunk or key set circuit as shown in Fig. 12. There will be one relay 699^r for each set of tens and units relays.

The ten tens relays, Fig. 11, contain contacts to which are connected the secondary trunks such as shown in Fig. 9. For a complete set of relays there will be 100 secondary trunks connected. As each secondary trunk, Fig. 9, is capable of serving 100 primary trunks or 1000 lines, it therefore follows that the tertiary trunk which has access to 100 secondary trunks is capable of serving 100000 lines. Of course the group of secondary and primary trunks can be arranged to suit traffic conditions and instead of providing a group of 100 secondary trunks, each trunk serving a certain separate group of 100 primary trunks, the grouping can be so arranged that a group of ten secondary trunks can be made to serve the same set of 100 primary trunks, and in such an event, the tertiary trunk would serve 10,000 instead of 100,000 lines. This grouping however can be arranged to suit the exchange requirements as it is only necessary to provide enough secondary and tertiary trunks to allow calling subscribers to be answered promptly.

Referring to Fig. 12, the main circuit of the tertiary trunk or key set is shown. Relay 668 is operated when the tertiary trunk is connected to the secondary trunk. The operation of this relay lights the call lamp 702 and guard lamp 701, Fig. 13, notifying the operator of a call. The operation of relay 668 causes the operation of relay 663 which renders this particular trunk busy against other incoming calls and also transfers the starting wire to the next trunk in order. Relay 660 is the answering relay and is operated when the button 703, Fig. 13, is pressed. The operation of this relay connects the operator's telephone set (indicated at A-B) to the tip and sleeve conductors so as to allow her to converse with the calling subscriber. The operation of this relay also completes the circuit of the lamp 700 which will continue to glow as long as relay 660 is energized. Relay 661 is the starting relay and is operated when the starting button 705 is pressed. The circuit of this relay is controlled over the third conductor leading to the secondary trunk. The operation of relay 661 releases the answering relay 660 and energizes relay 664. The operation of relay 664 also closes the circuit of the guard lamp 701, which will continue to glow while the connection is being established. The operation of relays 661 and 664 place the shifting switch X², Fig. 13, in

operative condition and also place the control relay 718 in series with the stepping relay of the first selector over the tip side of the trunk. This relay 718 controls the stepping of the switch X' which in turn controls the stepping of switch X^2 . The operation of relay 718 is controlled by the various stepping relays of the selector and connector switches.

10 The circuit of a stepping relay is opened once at each step of the switch with which it is associated and it necessarily follows that relay 718, which is in series with the stepping relay operates in unison with it and in 15 operating causes the switch X' to take a number of steps corresponding to the number of times the circuit is opened. The switch X' will continue to step until the depressed button on the keyboard is reached 20 whereupon the switch X^2 takes a step, disconnecting relay 718 from the tip side of the trunk and connecting it to the sleeve side of the trunk.

The switch X^2 consists of three portions, 25 734, 735, and 736: each portion consists of a wiper and a bank of contacts. The contacts in the portion 734 are arranged so as to shift relay 718 to either the tip or sleeve conductors of the trunk through the contacts 30 of relay 666. This latter relay has its circuit closed when the operator presses the button 706. This relay is simply used so the operator can shift the connection from one sending device to another in case duplicates are provided. There would be one relay 666 for each device. Where only one sending device is provided for each tertiary trunk, this relay can be omitted and the wires, which are shown passing through 35 its contacts, can be permanently connected. The portion 735 of switch X^2 is so wired that the common wire of the strip of the buttons 707 is connected to the first contact in the bank. The third contact in the bank 40 is connected to the strip of buttons 708, the fifth contact to the strip of buttons 711 and the seventh contact to strip 709 and the ninth contact to the strip 710. The second, fourth, sixth, eighth and tenth contacts are 45 connected to the winding of relay 717.

When the wiper of the portion 735 engages one set of contacts to which the relay 50 717 is connected the wiper of the portion 734 engages a contact leading to the sleeve side of the trunk. In this position the test impulse is transmitted and relay 717 is operated and in turn operates relay 720 which in acting, operates relay 719, thereby removing ground from the winding of the 55 control relay 718 so that as soon as a single impulse is sent over the sleeve side of the trunk, the circuit of relay 718 is opened and remains open until the wiper of the portion 733 of the switch X' reaches the contact

which is permanently grounded. When this 65 contact is reached, the circuit of the stepping magnet 712 of the switch X^2 is closed causing the switch to take a step and the wiper of the portion 734 to leave the sleeve contact and the wiper of the portion 735 to 70 leave the contact to which relay 717 is connected. Relay 717 falling back places the control relay 718 in operative condition.

The switch X' is provided with two sets of bank contacts, each set of banks being 75 provided with an individual wiper. The first bank contact in portion 733 is connected permanently to ground while the other contacts are connected in order to the strips of keys or buttons from one to ten. 80 The portion 732 of the switch X' is arranged for restoring the switch to its normal position. The switch X^2 takes two steps at each complete rotation of the switch X' . These two steps are taken when the wiper of the 85 portion 732 of the switch X' engages a contact leading to the depressed button in the row and when the permanently grounded contact is engaged.

The switch X' is the first to restore and 90 after the wiper of the portion 732 reaches its normal position as shown in the drawing, the circuit of the stepping magnet 712 of the switch X^2 is completed and this magnet 95 will continue to vibrate until the switch X^2 reaches its normal position. The key-board shown in Fig. 13 consists of five rows of buttons, there being ten buttons to each row. These buttons are of the usual locking or indicating type and arranged so that when 100 any button in the row is pressed, it will release the button formerly pressed. The buttons 703, 704 and 705 are of the usual non-locking type. Button 706 keeps its contacts closed when pressed, and maintains them 105 closed until restored by the operator.

Referring again to Fig. 12, the circulator switch S does not step once for each call as do the previously mentioned switches K, L and T. This switch S is operated by 110 ground connected to the starting wire 628 through the contacts of relay 583, Fig. 10, and in case of failure of relay 656, Fig. 12, to operate. Under normal operating conditions, the master relay 583 is only momentarily energized, the duration of the energizing circuit being while the tertiary trunk is selecting the secondary trunk. If, however, ground is connected to the starting wire 628 and relay 656 fails to operate, then 115 120 the circuit of relay 658, Fig. 12, is closed as follows:

Ground being placed on the starting wire 628 closes the circuit of relay 697 through the back contacts of relays 656, 658 and 125 698. The operation of relay 697 completes the circuit of relay 698 which in acting opens the circuit of relay 697. This latter

relay then falls back and the circuit of relay 658 is closed through the back contacts of relay 697 and upper contacts of relay 698 as the latter relay is very slow in restoring.

10 The operation of relay 658 completes the circuit of magnet 669 causing the switch S to step. It will be noted that the circuits of the relays 697, 698 and 658 are closed through the contacts of relay 656 by ground placed on the starting wire 628.

15 The locking circuit of relay 658 is controlled by ground over the starting wire and the operation of this relay completes the circuit of the stepping magnet 669 of the switch S through the back contacts of relay 657. The switch S will start to step and continue stepping until the starting wire is connected beyond the open contacts in the series and so energize relay 656, Fig. 12 and relay 699, Fig. 11 in series. As soon as this latter relay is operated, the master relay 583 is released, thereby causing the switch S to cease rotating.

20 25 Referring to Fig. 14, the method of guarding a complete set of series contacts in the primary control relays is shown. These relays are numbered and correspond to the relays of the same numbers in Fig. 6. This Fig. 14 also shows the method of guarding the series contacts in a group of ten primary trunks. Relays 110^a, 125^a and 124^a correspond to relays 110, 125 and 124, in Fig. 2. It will be noted that the series starting circuit for each trunk is controlled through the contacts of the three relays just mentioned. The set of primary control relays 321 to 330 inclusive have their series contacts controlled or guarded 30 by the portion 360 of the switch K while the series contacts of the control relays 341 to 350 inclusive are guarded by the portion 361 of the switch K. The starting wires for the series contacts of the primary trunks are controlled by the portion 362 of the switch K.

35 40 45 It will be noted that when the switch K is in the position shown in the drawing and all the primary trunks of a particular set are idle, that the initial action of the various circuits is controlled from the first set of contacts of the switch K. In order to show how the switch K guards the series contacts of relays 321 to 330 inclusive and 341 to 350 inclusive, we will assume that relay 322 is energized, but the back contact of relay 321 is open, due to a faulty connection. While relay 322 is energized, and the preceding contact open, its action 50 is ineffective and it cannot operate its associated relay 332. As relay 332 cannot be operated, it naturally follows that the tens and units relays of the primary set, Fig. 1, cannot be operated.

55 60 65 By referring to Fig. 6 it will be seen that

the stepping magnet 353 of the switch K however will have its circuit completed by each operation of relay 359, or if 363 is deenergized sufficiently long to close its back contact. The stepping of the switch K removes ground from the contact of relay 321 and transfers it to the contact of relay 322. The operation of relay 322 is now effective as the ground is connected directly to its contacts through the portion 360 of the switch K. When the switch K takes this step, the trunk next selected will be the second primary trunk. In the first instance, the wiper of the portion 362 of the switch K rests upon the contact connected to the starting wire of the first trunk, but after taking a step in order to pass the open contact of relay 321 the starting circuit is connected to the second primary trunk of the set. From the foregoing description, it will be noted that the switch K will continue to step until the open contact in the series is passed and in case relay 328 was energized and the open occurred in the contact of relay 327, then the switch K would take eight steps until ground was connected to the contact of relay 328. In case of an open contact in relay 341 of the set 341 to 350, and 322 was the relay energized in the set 321 to 330, then the operation of relay 322 would close the circuit of relay 332 and allow the tens relay 2, in the primary set to become operated but the circuit of the units relay would not be closed, as it depends upon the operation of a relay in the set 341 to 350. The switch K will continue to step and in case relay 342 is the relay energized, the stepping of the switch will connect ground past the open contact of relay 341 directly to the contact of relay 342. When this step is taken however, relay 352, Fig. 6, is also operated, thereby removing ground from the contacts of the energized line relay, thereby releasing relays 322, 332 and 358. These relays only drop back momentarily however, but the effect of this momentary falling back allows the tens relay 2 of the first primary trunk to restore. In order to effect connection between the calling line and the trunk, it is necessary to energize a tens and units relay of the same set. In this instance the tens and units relays associated with the second trunk will be operated as the action of relay 342 is rendered effective when the switch K steps to the second trunk. In case of an open contact in the starting wire of the primary trunks no selection is made until portion 362 of the switch K is stepped beyond the break. In order to take care of such a contingency, the slow relays 363 and 351 are provided. The relay 363 normally has its circuit completed through the back contacts of the relay 358. This latter relay is operated by one of the relays of 70 75 80 85 90 95 100 105 110 115 120 125 130

the set 321 to 340 and which under normal conditions is only momentary, for as soon as the calling line is connected to the primary trunk, the circuit of relay 358 is broken. Ordinarily the momentary action of relay 358 does not allow relay 363 to fall back, but in case of an open in the starting wire, relay 358 is held energized for an appreciable length of time, thereby allowing relay 363 to fall back. The falling back of this relay causes the stepping of switch K as shown later. Alarm relay 351 is controlled by relay 352.

Referring to Fig. 15, the method of guarding the secondary control circuit is identical with that of Fig. 14. The starting wires leading from the portion 480 of the switch T, instead of passing through the contacts of the three relays such as 110^a, 125^a and 124^a, are shifted through the contacts of two relays, such as 555^a and 401.

Referring to Fig. 16, the method of guarding the tertiary set of control relays and the tertiary trunks is shown. In the present instance, the sets of series contacts in the two groups of relays 451 to 460 and 571 to 560 are guarded by switch L, this switch being provided with the two portions 636 and 637. This switch L is operated or stepped once at each call under normal operating conditions.

The switch S which guards the set of series contacts of the tertiary trunks is provided with one set of bank contacts and wiper shown in the portion 699^w. This switch only steps under abnormal conditions, that is when there is any undue delay in effecting proper connections between the secondary and tertiary trunks. In case of any such delay, the switch S will start to step and continue to step until a tertiary trunk is placed in operative condition. In this figure, relays 663^a to 663^j represent relays in tertiary trunks. Relay 663^a corresponds to relay 663, Fig. 12, while relays 665^a and 659^a correspond to relays 665 and 659, Fig. 12.

The difference between the tertiary control and the primary and secondary control is that the control relays are guarded by switch L, while the series contacts in the tertiary trunks are guarded by an individual switch S, which acts independently of the switch L. By this method the key-sets are placed in service in regular order, the first idle one being the one selected.

We will now trace a connection from the calling to the called subscriber and arrange the various figures as shown in Fig. 17 and use the ten party connector shown in Fig. 4^a.

We will assume that subscriber A, whose number is 1021, desires to call subscriber AA. The subscriber at station A, removing his receiver, closes the circuit of the line relay 42, through the contacts of the cut-off

relay 41. The operation of relay 42 closes the circuit of relay 321 over the tens starting wire by the following path: ground, contacts of relay 364, wire 87, contacts of relay 352, 71, contacts of relay 42, 72, contacts of relay 358, 306, 321, to battery B. The operation of relay 321 closes the circuit of relay 358, thereby opening the group of tens starting wires. Relay 321 having operated however, its circuit is maintained locked directly to wire 72. The operation of relay 321 also closes the circuit of relay 331 by the following path: ground, portion 360 of the switch K, 318, contacts of relay 321, 308, 331 to battery B. The operation of relay 331 allows the circuit of relay 341 to be closed by the following path: ground, contacts of relay 364, wire 87, contacts of relay 352, 71, contacts of relay 42, 73, contacts of relay 331, 301, contacts of relay 359, 302, 341 to battery B. The operation of relay 341 closes the circuit of relay 359. The operation of this latter relay opens the group of units starting wires to prevent any further action of the set of relays 341, 342, 343, etc. The circuit of relay 341 is however maintained locked to ground over wire 301. The operation of relay 359 closes the circuit of the control relay 382, Fig. 1, by the following path: ground, contacts of relay 359, 315, 354, 316, portion 362 of the switch K, 83, contacts of relay 110, contacts of relay 125, 85, 382 to battery B. The operation of relay 382 closes the tens and units starting wires to its group of tens and units relays. The circuit of the tens relay is now completed by the following path: ground, contacts of relay 331, 81, contacts of relay 382, relay 1 to battery B. The circuit of the units relay 11, Fig. 1, is closed by the following path: ground, portion 361 of the switch K, contacts of relay 341, 79, contacts of relay 382, 11, to battery B.

The operation of the tens relay 1 and the units relay 11 of the primary set connect the calling line to the primary trunk, Fig. 2. At the same time relay 382 is operated, the circuit of the slow relay 124, Fig. 2, is closed by the following path: ground, contacts of relay 382, wire 84, winding of 124 to battery B. The operation of relay 124 opens the series starting wire leading to the next trunk in order so as to prevent a premature operation of the next idle trunk. The operation of relay 359 also completes the circuit of relay 355 by the following path: ground, contacts of relay 359, 88, contacts of relay 352, 310, 355 to battery B. The operation of relay 355 closes the circuit of the slow relay 356 through the back contacts of the slow relay 357. The operation of relay 356 allows the circuit of relay 357 to be closed by ground through the contacts of relay 355. The operation of relay 357 allows the circuit of relay 354 also to be

closed by ground through the contacts of relay 355. The operation of relay 354 completes the circuit of relay 352. The operation of this latter relay removes ground from the wire 71 which is common to a group of 100 line relays. Ground being removed in this manner from the contacts of the line relay 42 allows relay 321 to fall back. This relay falling back releases relay 358 and relay 331. Relay 341 is also released when the ground is removed from the contacts of relay 42. Relay 341 falling back releases relay 359. Relay 352 in pulling up also energizes alarm relay 351.

From the foregoing description it will be seen that as soon as the calling line becomes connected to the primary trunk and relay 352 operated, all parts of the control circuit, Fig. 6, are restored to their normal condition. As soon as the calling line is connected to the primary trunk, relay 110 is placed in series with the cut-off relay 41 by the following path: battery B, 110, 58, contacts of relay 11, 92, contacts of relay 1, 94, 41 to ground. The operation of relay 41 disconnects the line relay 42 and the resistance coil from the calling line. Relay 110 being energized and relay 124 falling back, connects the starting wire 83 to the next primary trunk in order. When relay 355, Fig. 6, has its circuit closed from ground through the contacts of relay 359, it closes the circuit of the stepping magnet 353 of the switch K. The operation of this magnet causes the switch to take one step and place the next primary trunk, in case it is idle, in condition to be operated by the next call. The stepping of the switch K also changes the location of the ground connection of the series control contacts in the relays 321, 322, 323, etc., and 341, 342, 343, etc. As soon as ground is removed from the winding of relay 355 by the operation of relay 352 the circuit of the stepping magnet 353 is broken and no further action of the switch takes place.

When the tens and units relays 1 and 11, Fig. 1, are energized, their circuits are maintained locked to ground through the contacts of relay 110 which is energized, and the back contacts of relay 125, which is deenergized. The locking circuit for the tens relays passes through a suitable resistance coil. This coil is simply used to reduce the current consumption. The tens relays which carry a large number of contacts can be low wound so that at the initial closing of their circuits, they will operate quickly and will then be held energized through the resistance coil. As soon as relay 110 becomes energized, the circuit of relay 382 is broken, thereby opening all starting wires leading to tens and units relays of its set. Relay 121 corresponds to, and acts in the same manner as line relay 42, insomuch

as it closes the circuits of the tens and units starting wires. These starting wires pass through the back contacts of relay 113 which corresponds to the cut-off relay 41. The operation of relay 121 closes the circuit of relay 421, Fig. 7, by the following path: ground, contacts of relay 470, 105, contacts of relay 121, contacts of relay 113, 106, contacts of relay 471, 421 to battery B. The operation of relay 421 completes the circuit of relay 471 thereby opening the tens starting wires and preventing any other relay of the set 421, 422, 423, etc., becoming operated. The operation of relay 421 completes the circuit of relay 431 by the following path: ground, portion 478 of the switch T, 413, contacts of relay 421, 431 to battery B. The operation of relay 431 allows the circuit of relay 441 to be closed by the following path: ground, contacts of relay 470, 105, contacts of relay 121, contacts of relay 113, 107, contacts of relay 431, contacts of relay 472, 441 to battery B. The operation of relay 441 closes the circuit of relay 472, which in operating, opens its set of units starting wires. The operation of relay 472 connects ground to the starting wire 407 and operates relay 419 associated with a set of tens and units relays, Fig. 8, by the following path: ground, contacts of relay 472, contacts of relay 476, portion 480 of the switch T, 407, contacts of relay 555, Fig. 9, contacts of relay 552, 502, 419 to battery B. The operation of the relay 419 allows the circuit of the tens relay 521, Fig. 8, to be closed by the following path: ground, contacts of relay 431, 404, contacts of relay 419, 491, 521 to battery B. The operation of relay 419 also allows the units relay 531 to be operated by the following path: ground, portion 479 of the switch T, 410, contacts of relay 441, contacts of relay 419, 494, 531 to battery B.

The operation of the tens relay 521 and the units relay 531 connects the primary trunk, Fig. 2, to the secondary trunk, Fig. 9. As soon as this connection is effected, relay 114, Fig. 2, is placed in series with relay 552 by the following path: battery B, 114, contacts of relay 115, 108, contacts of relay 521, 508, contacts of relay 531, 518, contacts of relay 555, 541, 552 to ground. The operation of relay 552 closes the circuit of relay 556 and places ground on the locking wire 543 leading to the tens and units relays 521 and 531. The operation of relay 556 completes the circuit of relay 555. The operation of this latter relay disconnects relay 552 and ground is then maintained to the locking contacts of relays 521 and 531 through the contacts of relay 556. The circuit of relay 556 is maintained locked to ground through the back contacts of relay 600.

After the secondary trunk has been selected, all parts of the control circuit, Fig. 130

7, are restored to normal condition in the following manner; the winding of relay 401 is placed in multiple with the winding of relay 419 through the back contacts of relay 555. Relay 401 is a slow acting relay in restoring, and is only momentarily operated because relay 555 is operated as soon as relay 556 has its circuit closed by the action of relay 552. The operation of relay 401 closes the circuit of relay 477 through the back contacts of relay 470. The operation of relay 477 connects ground to the winding of the stepping magnet 475 thereby causing the switch T to take one step. The operation of relay 477 also completes the circuit of the slow relay 474. The operation of relay 473, which has its circuit momentarily closed when relay 474 is operated, closes the circuit of relay 476. The action of this latter relay completes the circuit of relay 470 and this relay in operating removes ground from wire 105 leading to the contacts of relay 121, Fig. 2. The removal of this ground as well as the operation of relay 114 closing the circuit of relay 113, allows relays 421, 431, 441 and consequently relays 471 and 472, to return to their normal positions. The operation of relay 113 disconnects the tens and units starting wires of its primary trunk.

When the primary trunk and secondary trunk are first connected through the tens and units relays of the secondary set, the only relays remaining energized are 555 and 556, the operation of the former disconnects the starting wire from its trunk and continues it on to the next trunk in order. The operation of relay 556 connects ground to the third conductor 545, thereby completing the circuit of relay 585, Fig. 10, by the following path: ground, contacts of relay 556, 557, contacts of relay 553, 558, contacts of relay 600, 545, contacts of relay 587, contacts of relay 586, 585 to battery B. The operation of relay 585 completes the circuit of relay 451 over the tens starting wire by the following path: ground, back contacts of relay 589, 597, contacts of relay 585, 598, contacts of relay 581, 641, 451 to battery B. The operation of relay 451 completes the circuit of relay 581, thereby opening the tens starting wires. The operation of relay 451 also completes the circuit of relay 561 by the following path: ground, portion 636 of the switch L, 633, contacts of relay 451, 626, 561 to battery B. The operation of relay 561 allows the circuit of relay 571 to be closed by the following path: ground, contacts of relay 589, 597, contacts of relay 585, 624, contacts of relay 561, 625, contacts of relay 583, 642, 571 to battery B. The operation of relay 571 completes the circuit of relay 583 which in acting opens the units starting wires of its set. The operation of relay 583 closes the circuit of relay 699,

Fig. 11, belonging to a set of tertiary tens and units relays, by the following path: ground, contacts of relay 583, 628, relay 656, 670, portion 699^w of the switch S, 671, contacts of relay 663, 672, contacts of relay 665, 70 contacts of relay 662, 651, 699^r to battery B. The operation of relay 699 allows the tens and units relays 601 and 611 to be operated. The circuit of relay 601 is closed by the following path: ground, contacts of relay 561, 629, contacts of relay 699^r, 643, 601 to battery B. The circuit of relay 611 is closed by the following path: ground, portion 637 of the switch L, 593, contacts of relay 571, 631, contacts of relay 699^r, 644, 611 to battery B. 80 The operation of the tens and units relays, Fig. 11, connects the secondary trunk, Fig. 9, to the tertiary trunk, Fig. 12. As soon as this connection is effected, the circuit of relay 586, Fig. 10, and relay 668, Fig. 12, 85 are closed by the following path: battery B, relay 662, contacts of relay 664, 648, contacts of relay 611, 646, contacts of relay 601, 514, contacts of relay 587, 586, 513, contacts of relay 601, 647, contacts of relay 611, 650, 90 contacts of relay 664, 668 to ground. The operation of relay 586 disconnects relay 585 from the third conductor 545. Relay 585 falling back must release relay 451 and consequently relays 581, 561, 571 and 583. 95 These relays are however released in another manner after the tertiary trunk has been selected as follows: As soon as relay 583 operates, ground is connected to the winding of relay 588 through the back contacts of relay 589. The operation of the former relay connects ground to the stepping magnet 590 of the switch L, causing it to take one step. The operation of relay 588 also completes the circuit of relay 592 through the 105 back contacts of relay 591. The operation of relay 592 thereupon completes the circuit of relay 591. As soon as relay 591 becomes energized, the circuit of relay 592 is broken and it falls back. As soon as relay 592 falls 110 back, the circuit of relay 589 is completed by the following path: ground, contacts of relay 588, 599, contacts of relay 592, 621, contacts of relay 591, 594, 589 to battery B. The operation of relay 589 removes ground 115 from the contacts of relay 585, thereby releasing the set of relays formerly mentioned. Under normal conditions, the time necessary to operate relay 589 in the manner just described allows the tens and units relays of 120 the tertiary set, Fig. 11, to be operated and their circuits locked to ground through the back contacts of relay 665, Fig. 12. The operation of relay 662, Fig. 12, opens the circuit of relay 699^r, Fig. 11. 125

The operation of relay 668, Fig. 12, completes the circuit of relay 663, which has its locking contact connected to ground through the back contacts of relay 665. The operation of relay 663 opens the starting wire of 130

its trunk and connects it to the next trunk in order, through the back contacts of relay 659. This latter relay was operated by ground through the contacts of relay 699, 5 when its circuit was first closed. Relay 659 is slow in restoring and maintains the starting circuit open for a short period to prevent any possible interference between trunks. The operation of relay 668 completes the circuits of the guard lamp 701 and the call lamp 702, Fig. 13, notifying the operator of a call.

After the tertiary selection has been completed battery and ground are connected to 15 the tip and sleeve conductors leading to Fig. 9, this battery and ground being furnished through the winding of the relay 662 and relay 668, Fig. 12. Relay 551 being bridged across the tip and sleeve conductors through 20 the back contacts of relay 550 becomes operated and in operating completes the circuit of the slow acting relay 553. This latter relay completes the circuit of relay 554. The operation of the slow relay 553 opens 25 the third conductor 545.

The operator, upon getting the calling signals indicated by the glowing of the lamps 701 and 702, locks the key 706 thereby energizing control relay 666 so as to place 30 her sending device and key-board in operative condition. After this button is locked, she then presses the answering button 703, thereby completing the circuit of relay 660 and closing the circuit of the lamp 700. 35 This relay in operating connects the operator's telephone set directly across the tip and sleeve conductors and breaks the circuit controlling the lamps 701 and 702. The operator, after conversing with the calling 40 subscriber and asking for the number desired, sets up the number on her key-board and presses the starting button 705, which closes the circuit of the starting relay 661 by the following path: ground, 705, 746, contacts of relay 666, 684, 661, 649, contacts of relay 611, 645, contacts of relay 601, 634, 587, 545, upper contacts of relay 553, 542, 550 to battery B. The operation of relay 550 disconnects the bridged relay 551 and 45 connects relay 600 in series with relay 114, Fig. 2. The operation of relay 600 maintains relay 550 in series with relay 587, Fig. 10, and relay 661, Fig. 12, after the slow relay 553 restores. The restoration of relay 553 is caused when relay 551 falls back. 50 The operation of relay 600 also releases relay 556 but maintains the circuit of relay 554 closed before the slow relay 553 releases. The action of relay 554 maintains ground on 55 the locking contacts of the tens and units relays, Fig. 8 and also maintains the circuit of relay 555 closed so as to prevent this particular trunk being used by other calls and to cause the starting wire to be continued to

the next trunk in order. The operation of relay 661 releases relay 660 and closes the circuit of relay 664. The operation of this latter relay disconnects the relay 662 and relay 668 respectively from the tip and sleeve conductors and also completes the circuit of the guard lamp 701. This lamp will remain lighted while the connection is being established.

The operation of relay 661 connects the control relay 718, Fig. 13, in series with the stepping relay 122, Fig. 2 by the following path: ground, contacts of relays 719, 718, 755, portion 734 of the switch X^2 , 747, contacts of relay 666, 667, contacts of relay 661, 648, contacts of relay 611, 646, contacts of relay 601, 514, contacts of relay 531, 504, contacts of relay 521, 104, contacts of relay 114, 148, cam springs 127, 147, contacts of relay 123, 146, 122 to battery B. The operation of relay 122 closes the circuit of the 85 rotary magnet 120 of the switch D. This magnet in completing its stroke, closes the circuit of the relay 123 which in operating opens the circuit of relay 122 and consequently that of relay 718, Fig. 13. As soon 90 as the magnet 120 falls back after completing its stroke, the circuit of relay 123 is opened and it in falling back again places relay 122 in series with relay 718. At each opening and closing of the relay circuit 122, 95 the relay 718 is operated. The operation of relay 122 and 718 will continue and the switch X^2 will rotate in unison with the stepping or rotation of the switch D. The circuit of the stepping magnet 715 of the 100 switch X^2 is completed at each stroke of the relay 718 by the following path: ground, contacts of relay 718, 757, contacts of relay 717, contacts of relay 720, 738, 715 to battery B. The switch X^2 and the switch D will 105 continue to step until the wiper of the portion 733 of the switch X^2 reaches a contact leading to the key or button pressed in the row 707. As soon as such a contact is reached, the circuit of the magnet 712 of 110 the switch X^2 is completed by the following path: ground, portion 735 of the switch X^2 , 739, depressed button in the row 707, which we will assume to be the ninth, 729, 733, 737, back contacts of relay 717, 756, upper contacts of relay 718, which is energized at this instant, 754, 712 to battery B. The closing of the circuit of the magnet 712 causes the switch X^2 to take one step thereby disconnecting relay 718 from the tip conductor and 115 connecting it to the sleeve conductor. As soon as this relay is disconnected from the tip conductor, the circuit of relay 122, Fig. 2, is broken and the switch D comes to rest with its wipers in line with the ninth row of 120 contacts which corresponds to the ninth button depressed in the row 707, Fig. 13.

As soon as the switch X^2 takes its first

step, the circuit of relay 717 is closed through the portion 735. This relay operating closes the circuit of relay 720. The operation of this latter relay completes the circuit of relay 719 after relay 718 falls back. As soon as the switch X^2 takes the first step, relay 718 is placed in series with the test relay 119, Fig. 2, by the following path: ground, contacts of relay 719, 718, 755, 734, 748, contacts of relay 666, 650, contacts of relay 611, 647, contacts of relay 601, 513, contacts of relay 531, 503, contacts of relay 521, 103, contacts of relay 114, cam springs 127, 119 to battery B. When energized, relay 119 locks itself to ground through the cam springs 128 by the following path: battery B, relay 119, locking contact of relay 119, contact of relay 116, wire 139, contact of relay 125, wire 144, cam springs 128, to ground. The operation of relay 718 is only momentary for as soon as relay 119 becomes energized, it locks itself directly to ground through the cam springs 128, of the switch D, thereby shunting relay 718. Even if relay 718 does operate, it cannot effect the stepping magnet 715 as relay 717 is energized thereby opening the circuit of the magnet. The circuit of the magnet 715 however is closed by the operation of relay 720 as follows: ground, portion 732 of the switch X' , contacts of relay 716, 760, contacts of relay 720, 738, 715 to battery B. Magnet 715 in completing its stroke will complete the circuit of relay 716 thereby causing the magnet's circuit itself to be opened. The switch X' will continue to step and when the permanently grounded contact of the portion 733 is reached, the circuit of magnet 712 of the switch X^2 will be closed as follows: ground, 733, 737, contacts of relay 717, 754, 712 to battery B. The magnet 712 having its circuit closed will cause the switch X^2 to take another step thereby releasing relay 717, 720 and 719 and place relay 718 again to the tip conductor through the portion 734.

After the test impulse has been delivered to the relay 119 and while the switch X' is rotating, the circuit of the vertical magnet 118 of the switch D is closed by the following path: ground, cam springs 128, contacts of relay 119, contacts of relay 116, 118 to battery B. The operation of magnet 118 causes the switch D to step vertically and also closes the circuit of relay 116 thereby breaking the magnet circuit itself. The circuit of relay 119 is maintained closed by the wiper 142 engaging busy or grounded contacts and to ground by the following path: ground, cam springs 128, 144, back contacts of relay 125, 139, contacts of relay 116, locking contact of 119, winding of 119, to battery B. As soon as the wiper 142 of the switch D engages an idle contact and relay

116 is energized, then the circuit of relay 65 119 is no longer maintained and it immediately falls back, opening the circuit of the vertical magnet 118 causing the switch D to come to rest with its wipers engaging contacts leading to an idle second selector 70 such as shown in Fig. 3. While relay 119 is energized, the circuit of relay 117 is closed the action of which severs the tip and sleeve conductors while the wipers of the switch D are passing over busy contacts. 75

It will be noted that even though relay 718, Fig. 13, is connected to the tip conductor in the manner just explained, its circuit is maintained open while the switch D is stepping and picking out an idle trunk. 80 While this switch is stepping vertically, relay 117 is energized and opens the tip and sleeve trunk conductors and prevents the operation of relay 718. However when the switch D picks out an idle trunk and the 85 relay 718 is connected to the tip conductor, its circuit is completed in series with relay 162, Fig. 3. The operation of relay 162 completes the circuit of the rotary magnet 166 of the switch E and the rotary magnet 90 in operating completes the circuit of relay 169, thereby breaking the series circuit between relay 162 and relay 718. As soon as the rotary magnet 166 completes its stroke and drops back, then the circuit of relay 95 169 is again broken, allowing relays 162 and 718 to again be placed in series. The vibrating or stepping effect between these two relays will continue until the wiper of the portion 733 engages a contact leading to the 100 button depressed in the row 708. We will assume that the second button is the one depressed, whereupon the circuit of the magnet 712 of the switch X^2 will be closed by the following path: ground, 735, 740, second 105 button in the strip 708, 722, 733, 737, back contacts of relay 717, 756, upper contacts of relay 718, 754, 712, to battery B. Magnet 712 having its circuit closed will cause the switch X^2 to take another step thereby connecting relay 718 to the sleeve conductor and placing ground to the winding of relay 717. The action of relay 717 completes the circuit of relay 720 as before and when the relay 718 falls back, the circuit of relay 115 719 is closed, preventing any further operation of the relay 718. When the switch X^2 steps and places relay 718 to the sleeve conductor, its circuit is completed through the winding of test relay 167, Fig. 3. The operation of relay 720, Fig. 13, allows the circuit of magnet 715 to be closed through the portion 732 of the switch X' and this switch will continue to rotate as before until the permanently grounded contact of the portion 733 is reached, whereupon the circuit of the stepping magnet 712 is completed 120 and the switch X^2 caused to take another

step. In taking this step, the circuit of the relay 717 is broken and consequently the circuit of relays 720 and 719 are opened thereby placing relay 718 again to the tip conductor.

After the wiper of the portion 733 of the switch X' passes the grounded contact, before the switch E picks out an idle contact, the switch X' will come to rest in the position shown in drawing, Fig. 13, as the circuit of the magnet 715 is broken when the wiper of portion 732 reaches its normal position. As soon as the second selector E picks out an idle trunk, the circuit of the relay 718 is completed through the winding of the stepping relay 970, Fig. 4^a. While the switch E is stepping vertically, the circuit of relay 164 is closed and in acting it severs the tip and sleeve conductors and prevents interruption while the wipers of the switch E are passing over busy contacts and also prevents the action of relay 718, Fig. 13.

As soon as the relays 718 and 970 Fig. 4^a are placed in series they will have their circuits opened and closed a number of times corresponding to the button depressed in the party line row 711, Fig. 13. The action of relay 718 causes the switch X' to rotate while the action of relay 970 completes the circuit of the stepping magnet 981 of the switch F' by the following path: ground, contacts of relay 970, 992, contacts of relay 991, 939, 981, 940, contacts of relay 977, 949 to battery D. The operation of relay 970 also completes the circuit of relay 975 which when energized, has its circuit locked to the test wire 935 through the contacts of relay 972. The test wire is grounded through the back contacts of relay 161, Fig. 3, and the test wiper 172. Magnet 981 of the switch F' will continue to step, due to the action of relay 970 until the wiper of the portion 733 of the switch X' reaches the button depressed in the strip 711. We will assume that the third button is the one depressed and as soon as the contact leading to this button is reached, the circuit of the magnet 712 of the switch X^2 will be completed by the following path: ground, 735, 743, third button in the strip 711, 723, 733, 737, contacts of relay 717, 756, contacts of relay 718, 754, 712, to battery B. The operation of the magnet 712 causes the switch X^2 to step, thereby connecting relay 718 to a blank contact and also completing the circuit of relay 717 through the portion 735. The operation of relay 717 now energizes relay 720 which in turn at once energizes relay 719 as the circuit of relay 718 is opened as the wiper of the portion 734 rests on a blank contact. The circuit of the magnet 715 of the switch X' will be completed by relay 720 and this switch will continue to step until the grounded contact in the portion 733 is reached, whereupon the

circuit of magnet 712 will be completed and cause the switch X^2 to step. This switch in stepping, removes the winding of relay 718 from the blank contact and connects it to the sleeve contact in series with relay 972, Fig. 4^a. The switch X^2 in stepping also releases relay 717, 720 and 719. The circuits of relays 972 and 718 will now be opened and closed a number of times corresponding to the button depressed in the strip 709. The operation of relay 972 completes the circuit of the rotary magnet 990 by the following path: ground, contacts of relay 972, cam springs 996, 990 to battery B. The magnet 990, at each stroke, closes the circuit of relay 971, thereby opening the circuits of relays 972 and 718. The operation of relay 972 releases relay 975 but closes the circuit of relay 991 by the following path: ground, contacts of relay 161, 80 Fig. 3, 172, 907, 935, contacts of relay 972, 991, 940, contacts of relay 977, 949 to battery B. The operation of relay 991 disconnects the stepping magnet 981 and in its place connects the vertical magnet 989. As soon as the wiper of the portion 733 of the switch X' reaches the depressed button in the row 709, which we will assume is the fourth button, the circuit of magnet 712 will be completed by the following path: 95 ground, 735, 741, fourth button in the strip 709, 724, 733, 737, contacts of relay 717, 756, contacts of relay 718, 754, 712 to battery B. The action of magnet 712 causes the switch X^2 to step, thereby breaking the 100 circuits of relays 718 and 972, causing the switch G' to bring its wipers in line with the fourth row of contacts in the bank. The shifting of the switch X^2 completes the circuit of the relay 717 which causes the 105 operation of relays 720 and 719. The circuit of relay 718 is broken as the wiper of the portion 734 comes to rest on a blank contact. The operation of relay 720 completes the circuit of the magnet 715 causing 110 the switch X' to rotate until the wiper of the portion 733 engages the grounded contact whereupon the circuit of magnet 712 is completed causing the switch X^2 to step, disconnecting relays 717, 720 and 719 and 115 connecting relay 718 to the tip conductor again in series with relay 970, (Fig. 4^a). The operation of relay 970 now closes the circuit of the vertical magnet 989 causing the switch G' to step vertically until the 120 wipers engage contacts corresponding to the button depressed in the row 710. The operation of relay 970 also completes the circuit of relay 975 which in turn completes the circuit of relay 979 by the following 125 path: ground, 916, 914, contacts of relay 975, 933, 979 to battery B. This relay is slow to restore and was also operated the first time relay 975 was energized, but at that time performed no functions. In the 130

present instance however the switch G' is stepping vertically and the wipers engage contacts of other lines which may be busy. The energizing of relay 979 severs the tip and sleeve conductors and prevents interference while the wipers are passing over contacts.

When the wiper of the portion 733 of the switch X' engages the button depressed in the row 710, which we will assume to be the fifth button, the circuit of the magnet 712 will be completed by the following path: ground, 735, 742, fifth button in the row 710, 725, 733, 737, contacts of relay 717, 756, contacts of relay 718, 754, 712, to battery B. The action of magnet 712 causes the switch X² to step disconnecting relays 972 and 718, thereby causing the wipers of the switch G' to engage the fifth set of contacts in the fourth row. The stepping of the switch X² places relay 718 to the sleeve conductor in series with relay 972 and also closes the circuit of relay 717. The operation of relay 717 completes the circuit of relay 720 and relay 718 remains energized in series with relay 972, until the switch X² takes a step when the circuit of relay 712 is closed by the wiper of the portion 733 engaging the grounded contact. As soon as this contact is reached, the operation of the magnet 712 causes the switch X² to take a step, thereby disconnecting relay 718 from the sleeve conductor. While the foregoing action is taking place, the operation of relay 972 connects the test relay 974 directly to the test wiper 966, which engages a contact leading to the cut-off relay of the called line. If the line is busy, relay 974 will become energized but if not, the relay will not be effected. After the test impulse is passed, that is to say when the circuits of relay 972 and 718 are broken, generator current is connected to the called line.

Referring again to Fig. 13, assuming the last step has been taken as mentioned, the circuit of the stepping magnet 715 is broken as soon as the wiper of the portion 733 passes the grounded contact. As soon as this contact is passed, the wiper of the portion 732 rests in the position as shown, thereby breaking the circuit of the magnet 715 and completing the circuit of the stepping magnet 712 of the switch X² in the following manner: as soon as the switch X² takes the last step, the circuit of relay 714 is closed to ground through the portion 736 of the switch X². The operation of this relay completes the circuit of the magnet 712 by the following path: ground, 732, normal resting contact of the switch X', contacts of relay 714, back contacts of relay 713, 712 to battery B. The operation of magnet 712 closes the circuit of the vibrating relay 713 and the operation of relay 713 opens the circuit of the magnet. The action thus set up

between the relay and the magnet causes the switch X² to be rotated until the circuit of relay 714 is broken, which will happen when the wiper of the portion 736 reaches its normal position. The circuit of relay 665, Fig. 76, 75, 80, 85, 90, 95, 100, 105, 110, 115, 120, 125, 130, 135, 140, 145, 150, 155, 160, 165, 170, 175, 180, 185, 190, 195, 200, 205, 210, 215, 220, 225, 230, 235, 240, 245, 250, 255, 260, 265, 270, 275, 280, 285, 290, 295, 300, 305, 310, 315, 320, 325, 330, 335, 340, 345, 350, 355, 360, 365, 370, 375, 380, 385, 390, 395, 400, 405, 410, 415, 420, 425, 430, 435, 440, 445, 450, 455, 460, 465, 470, 475, 480, 485, 490, 495, 500, 505, 510, 515, 520, 525, 530, 535, 540, 545, 550, 555, 560, 565, 570, 575, 580, 585, 590, 595, 600, 605, 610, 615, 620, 625, 630, 635, 640, 645, 650, 655, 660, 665, 670, 675, 680, 685, 690, 695, 700, 705, 710, 715, 720, 725, 730, 735, 740, 745, 750, 755, 760, 765, 770, 775, 780, 785, 790, 795, 800, 805, 810, 815, 820, 825, 830, 835, 840, 845, 850, 855, 860, 865, 870, 875, 880, 885, 890, 895, 900, 905, 910, 915, 920, 925, 930, 935, 940, 945, 950, 955, 960, 965, 970, 975, 980, 985, 990, 995, 1000, 1005, 1010, 1015, 1020, 1025, 1030, 1035, 1040, 1045, 1050, 1055, 1060, 1065, 1070, 1075, 1080, 1085, 1090, 1095, 1100, 1105, 1110, 1115, 1120, 1125, 1130, 1135, 1140, 1145, 1150, 1155, 1160, 1165, 1170, 1175, 1180, 1185, 1190, 1195, 1200, 1205, 1210, 1215, 1220, 1225, 1230, 1235, 1240, 1245, 1250, 1255, 1260, 1265, 1270, 1275, 1280, 1285, 1290, 1295, 1300, 1305, 1310, 1315, 1320, 1325, 1330, 1335, 1340, 1345, 1350, 1355, 1360, 1365, 1370, 1375, 1380, 1385, 1390, 1395, 1400, 1405, 1410, 1415, 1420, 1425, 1430, 1435, 1440, 1445, 1450, 1455, 1460, 1465, 1470, 1475, 1480, 1485, 1490, 1495, 1500, 1505, 1510, 1515, 1520, 1525, 1530, 1535, 1540, 1545, 1550, 1555, 1560, 1565, 1570, 1575, 1580, 1585, 1590, 1595, 1600, 1605, 1610, 1615, 1620, 1625, 1630, 1635, 1640, 1645, 1650, 1655, 1660, 1665, 1670, 1675, 1680, 1685, 1690, 1695, 1700, 1705, 1710, 1715, 1720, 1725, 1730, 1735, 1740, 1745, 1750, 1755, 1760, 1765, 1770, 1775, 1780, 1785, 1790, 1795, 1800, 1805, 1810, 1815, 1820, 1825, 1830, 1835, 1840, 1845, 1850, 1855, 1860, 1865, 1870, 1875, 1880, 1885, 1890, 1895, 1900, 1905, 1910, 1915, 1920, 1925, 1930, 1935, 1940, 1945, 1950, 1955, 1960, 1965, 1970, 1975, 1980, 1985, 1990, 1995, 2000, 2005, 2010, 2015, 2020, 2025, 2030, 2035, 2040, 2045, 2050, 2055, 2060, 2065, 2070, 2075, 2080, 2085, 2090, 2095, 2100, 2105, 2110, 2115, 2120, 2125, 2130, 2135, 2140, 2145, 2150, 2155, 2160, 2165, 2170, 2175, 2180, 2185, 2190, 2195, 2200, 2205, 2210, 2215, 2220, 2225, 2230, 2235, 2240, 2245, 2250, 2255, 2260, 2265, 2270, 2275, 2280, 2285, 2290, 2295, 2300, 2305, 2310, 2315, 2320, 2325, 2330, 2335, 2340, 2345, 2350, 2355, 2360, 2365, 2370, 2375, 2380, 2385, 2390, 2395, 2400, 2405, 2410, 2415, 2420, 2425, 2430, 2435, 2440, 2445, 2450, 2455, 2460, 2465, 2470, 2475, 2480, 2485, 2490, 2495, 2500, 2505, 2510, 2515, 8790, 8795, 8800, 8805, 8810, 8815, 8820, 8825, 8830, 8835, 8840, 8845, 8850, 8855, 88

generator current of the frequency selected, is connected to the called line and ringing current will be connected to this line until the disks reach their positions as shown in the drawing. Immediately following the ringing period and before the contacts 961 and 962 are closed, the contacts 919 and 921 are closed, energizing relay 998. The operation of this relay opens the circuit of relay 977 and short circuits the line of the called subscriber thereby removing any charge which may have accumulated on the line. If this provision was not made, then relay 977, especially in case of long lines, would receive a "back-kick" and prematurely unlock relay 991.

The called subscriber upon removing his receiver during a non-ringing interval, which will be when the disks are in the positions shown on the drawing, relay 977 will become energized and release relay 991.

At the termination of a conversation, the calling subscriber hangs up his receiver which causes relay 111, (Fig. 2), to fall back. The falling back of this relay opens the circuit of the slow relay 109. When this latter relay closes its contacts, the circuit of relay 115 is closed by the following path: ground, cam springs 128, 144, contacts of relay 125, 139, contacts of relay 116, 138, wiper 142, test contacts to wiper 143, 135, contacts of relay 109, 136, contacts of relay 117, 137, 115, to battery B. The operation of relay 115 releases relay 113 and completes the circuit of relay 125, by the following path: ground, contacts of relay 115, 134, 125 to battery B. The operation of relay 125 completes the circuit of the release magnet 149 by the following path: ground, cam springs 128, 144, contacts of relay 125, 149, to battery B. The operation of magnet 149 causes the switch D to restore. The operation of relay 125 also completes the circuit of relay 117. This relay in acting severs the tip and sleeve conductor while the switch D is restoring in order to prevent interference. As soon as the switch D reaches its normal position, the cam springs 128 are opened thereby releasing relay 115 and opening the circuit of the release magnet 149. The falling back of relay 115 releases relay 125.

As soon as relay 125 becomes energized by the action of relay 115, ground is removed from the locking wire 86, which passes through the upper contacts of relay 110. Ground being removed from this locking wire releases the tens relay 1 and the units relay 11 of the primary set, Fig. 1, thereby disconnecting the calling line from the primary trunk. As soon as the tens and units relays are released, relay 110, (Fig. 2), and the cut-off relay of the calling line are disconnected. As soon as relays 110 and 125 fall back, the starting circuit of the pri-

mary trunk is completed, thereby placing the trunk in operative condition.

As soon as the wipers of the switch D, (Fig. 2), leave the contacts of the second selector, (Fig. 3), the locking circuit of relay 163 is broken, as ground is removed from the test wire 152. As soon as relay 163 falls back, the circuit of relay 164 is completed by the following path: ground, cam springs 151, 154, contacts of relay 163, 155, 164 to battery B. The operation of relay 164 severs the tip and sleeve conductors and allows the circuit of the release magnet 168 to be closed by the following path: ground, back contacts of relay 167, 173, contacts of relay 164, 174, 168 to battery B. The operation of the release magnet causes the switch E to return to its normal position. While the switch E is restoring, ground is connected to the test wire 152 through the cam springs 151 and the back contacts of relay 163, thereby rendering the switch busy against the other calls until it has completely restored. When the switch restores, ground is removed from the test wire 152, and relay 164 by the opening of the cam springs 151. Relay 164 falling back opens the circuit of release magnet 168 thereby restoring all parts of the switch E to normal.

The called subscriber upon hanging up his receiver causes relay 977 to fall back, thereby completing the circuit of the stepping magnet 981 of the switch F' by the following path: battery B, 949, contacts of relay 977, 940, 981, 939, contacts of relay 991, contacts of relay 975, 937, I', 938, winding of 987, contacts of relay 988, 946, contacts of relay 977, 947, contacts of relay 991, 948, contacts of relay 975, to ground through contacts 914 and 916 controlled by the disk 915. The slow relay 987 in series with the winding of the magnet 981 operates and connects ground directly between its winding and the winding of magnet 981. The effect of this ground causes the magnet 981 to operate and step the switch F'. The operation of relay 987 closes the circuit of relay 988 thereby breaking the circuit of magnet 981. After an appreciable length of time, relay 987 falls back and releases relay 988 and the circuit is again closed as previously described. The vibrating action between the relays 987 and 988 and magnet 981 will continue until the wiper of the portion I' reaches its normal resting position, thereby breaking the circuit between wires 937 and 938 and preventing further action of the relays and the magnet. As soon as the wiper of the portion I' reaches its normal position, the wiper of the portion H' engages contact 999 thereby completing the circuit of the relay 985 by the following path: ground, cam springs 995, 941, H', 999, 985, to battery B. The operation of relay 985 closes the circuit of the release 13

5 magnet 986 causing the switch G' to restore and at the same time completes the circuit of relay 979, which in acting severs the tip and sleeve conductors to prevent interference while the switch is restoring. When the switch G' reaches its normal position, the cam springs 995 are opened and the circuit of relay 985 is broken and consequently that of magnet 986.

10 In case the called for subscriber does not answer, then the calling subscriber, upon hanging up his receiver, causes the release of the first and second selector switches. The release of the second selector switch removes ground from the test wire 907 of the connector switch, thereby unlocking relay 991. The releasing of relay 991 allows the restoring circuit of the switch F' to be closed in the manner previously described 15 and this switch upon restoring, causes the operation of the release circuit of the switch G'.

20 In describing how a connection is effected between a regular calling subscriber and a private branch exchange subscriber we will use Figs. 1, 2, 3, 4^b, 5, 6, 7, 8, 9, 10, 11, 12 and 13, arranged in accordance with Fig. 18. In this instance I will only trace in detail the circuits which have not been previously described.

25 The line of the calling subscriber is connected to an idle key-board in the manner previously described. The operator upon receiving the call for a subscriber in the private branch exchange sets up the proper number on her key-board. The method of operating the first selector, Fig. 2, and the second selector, Fig. 3, is the same as already described. The second selectors E, Fig. 3, 30 however, instead of picking out a regular connector such as shown in Figs. 4 and 4^a, picks out a private branch exchange connector as shown in Fig. 4^b. As soon as such a connector is picked out, the control relay 45 718, Fig. 13, is placed in series with relay 1070 over the tip conductor. The operation of relay 1070 completes the circuit of relay 1075 and also closes the circuit of the stepping magnet 1081 of the switch F², thereby 50 causing the wipers of this switch to take a number of steps corresponding to the button depressed in the strip 711, Fig. 13. As soon as the depressed button is picked out by the switch X' the switch X² steps, disconnects 55 relay 718 from the tip conductor and connects it to the sleeve conductor. Relay 718 is now placed in series with relay 1072, Fig. 4^b, over the sleeve conductor. The operation of relay 1072 releases relay 1075 and 60 completes the circuit of the rotary magnet 1090 of the switch G². This switch under the influence of the rotary magnet 1090, will rotate until the button depressed in the strip 709 is picked out by the switch X', Fig. 13. 65 The operation of relay 1072 also completes

the circuit of relay 1091 which upon acting disconnects the stepping magnet 1081 and in its place connects the vertical magnet 1089.

70 As soon as the button depressed in the strip 709 is picked out by the switch X', relay 718 is disconnected from the sleeve conductor and connected to the tip conductor by the stepping of the switch X². Relay 718 is now placed in series with relay 1070 over the tip conductor and the operation of the latter relay at this time completes the circuit of the vertical magnet 1089. 75

80 In calling for a subscriber in the private branch exchange where the trunks are connected to the first, second and third sets of contacts, etc., in the vertical row, the wipers of the switch G² will simply take a single step corresponding to the first button depressed in the strip 710. The operation of relay 1070 again completes the circuit of relay 1075 which in turn completes the circuit of slow relay 1079. The operation of this latter relay severs the tip and sleeve conductors to prevent interference when the wipers of the switch G² engage contacts of 85 busy lines or trunks. After the first button in the strip 710 is picked out by the switch X' the switch X² is caused to step thereby disconnecting relay 718 from the tip conductor and connecting it to the sleeve conductor 90 placing it in series with relay 1072, Fig. 4^b. The operation of relay 1072, which responds to the test impulse, connects the test relay 1074 to the best wiper 1066 of the switch G². If the first trunk or line leading to the 95 private branch exchange is busy, relay 1074 will become energized and instead of causing the release of switch G² will connect ground to the tip conductor 1050, thereby closing the circuit of relay 1070 by the following path; ground, contacts of relay 1074, 100 1050, contacts of relay 1076, contacts of relay 1071, 1027, winding of relay 1070 to battery B. The operation of relay 1070 completes the circuit of the vertical magnet 1089 and this magnet in acting closes the 105 circuit of the vibrating relay 1071 which opens the circuit of relay 1070. As soon as relay 1070 falls back the circuit of the vertical magnet 1089 is broken and it in falling 110 115 back releases relay 1071, thereby allowing relay 1070 to be operated again. This action will continue and the switch G² will step vertically until the wiper 1066 engages a contact of an idle trunk, whereupon relay 1074 falls back. The falling back of relay 1074 removes ground from the tip conductor preventing further action of relay 1070, and 120 also releases relay 1079 which was energized by the action of relay 1074. As soon as relay 1079 falls back the winding of relay 1076 is placed in series with the winding of the cut-off relay of the selected line or trunk. The operation of relay 1076 completes the 125 circuit of relay 1078 which in turn places the 130

- set of control or vibrating relays 1082, 1098 and 1084 into action so as to cause the stepping of the magnet 1083 of the auxiliary ringing switch M^2 . At the first step of this 5 switch the contact 1012 is disconnected from contact 1013 and connected to contact 1011, thereby connecting generator current of the character selected by the switch F^2 to the tip conductor. At the first step of the switch 10 the contact 1016 is disconnected from contact 1014 and connected to contact 1017, thereby connecting the grounded resistance coil 1018 to the sleeve conductor. Generator current now flows over the tip conductor 15 through the bell of the called subscriber back over the sleeve conductor to ground through the resistance coil 1018. At the first step of the switch M^2 the contact 1021 is disconnected from contact 1019 and connected to contact 1022. The closing of these two contacts connects ground to the winding of relay 1078, thereby maintaining the circuit of magnet 1083 closed until the contacts 1021 and 1022 are broken by the disk 1020 when 20 it reaches its normal position. The called subscriber removing his receiver when the switch M^2 is in the position as shown in the drawing, energizes relay 1077, thereby disabling the ringing circuit. 25 At the termination of the conversation the calling subscriber upon hanging up his receiver releases the first selector, second selector and primary relays in the manner previously described. The called subscriber 30 upon hanging up his receiver causes relay 1077 to fall back, thereby placing the stepping magnet 1081 under control of the vibrating or stepping relays 1087 and 1088 in the same manner as previously described in 35 connection with the magnet 981 and relays 987 and 988, Fig. 4^a. The switch F^2 will continue to rotate until the wiper of the portion I^2 reaches its normal position. When this contact is reached the wiper of portion 40 H^2 engages contact 1042, thereby completing the circuit of relay 1085 which in acting completes the circuit of relay 1079 which in acting severs the tip and sleeve conductors. The operation of relay 1085 45 also completes the circuit of the release magnet 1086, thereby restoring the switch G^2 to its normal position. 50 In case all of the trunks leading to the private branch exchange are busy, the switch G^2 will continue to step until the contacts of all the trunks are passed, whereupon the wiper 1009 engages a permanently grounded contact, thereby closing the circuit of relay 1008. The action of this relay connects a 55 suitable busy tone signal to the tip conductor of the trunk, notifying the calling subscriber that all the trunks are engaged. The wiper 1066 engages a blank contact, thereby causing the release of relay 1074 and

consequently the release of relay 1079. The 65 releasing of relay 1074 also removes ground from the tip conductor preventing further action of relay 1070. When the calling subscriber hears the busy signal and hangs up his receiver he will restore the first and second 70 selectors, primary relays and also the connector switch G^2 . When the second selector E, Fig. 3, restores, ground is removed from the test wiper 1007, thereby deenergizing relay 1091 and allowing the magnet 1081 75 of the switch F^2 to be actuated by the vibrating relays 1087 and 1088. When the switch F^2 reaches its normal position, the switch G^2 is caused to restore.

We will now describe in detail the operation of the two-wire trunk shown in Fig. 3^a and use Figs. 1, 2, 3^a, 4^a, 5, 6, 7, 8, 9, 10, 11, 12 and 13, arranged in accordance with Fig. 19. The line of the subscriber at A, who is calling for a subscriber in a different exchange is connected to an idle keyboard in the manner previously described and the operator sets up the proper number on her key-board. The first selector D, Fig. 2, is operated in the manner already described 80 and rotates until the wipers come opposite a row of contacts in which the terminals of a group of two-wire trunks are located. The switch then steps vertically and picks out an idle trunk such as shown in Fig. 3^a. 85 In describing the operation of Fig. 3^a, we will omit all detail references to the circuits previously described.

After an idle trunk is picked out, relay 812 is placed in series with the control relay 100 of the sending device over the tip conductor. The winding of relay 812 is connected to the tip conductor 830 by two paths, one of which is as follows: battery B, winding of relay 812, 835, contacts of relay 802 to 100 the tip conductor 830. The other path is as follows: battery B, winding of relay 812, 856, contacts of relay 819, 836, contacts of relay 823 to the tip conductor 830. The operation of relay 812 completes the circuit of relay 800 which in turn closes the circuit of relay 802 by the following path: ground, contacts of relay 813, 839, contacts of relay 800, 840, winding of relay 802 to battery B. After relay 802 is operated its circuit is 115 maintained locked to ground through the back contacts of relay 813. The operation of relay 802 opens one path by which the winding of relay 812 is connected to the tip conductor. The operation of relay 812 also 120 completes the circuit of the rotary magnet 808 by the following path: ground, contacts of relay 812, 837, contacts of relay 815, 838, cam springs 861, winding of magnet 808, to battery B. The operation of the magnet 808 125 closes its associated contact springs and completes the circuit of relay 823. The operation of relay 823 opens the other path by

which the winding of relay 812 is connected to the tip conductor 830. The operation of relay 823 therefore opens the circuit of relay 812 and the circuit of the control relay 5 of the sending device. The switch E' will continue to rotate until its wipers come to rest in line with the proper row of contacts. At the first step of the switch E' in a rotary direction, the cam springs 860 are 10 closed, thereby causing the operation of relay 820. The operation of this relay connects the winding of relay 813 to the sleeve conductor 831 by the following path: battery B, winding of relay 813, contacts of relay 820, 862, contacts of relay 819, 843, to the sleeve conductor 831. The operation of relay 820 also connects the winding of relay 813 to the sleeve conductor by another path as follows: battery B, winding of relay 813, 15 contacts of relay 820, 862, 842, contacts of relay 821, 843 to the sleeve conductor 831.

When the control relay of the sending device is connected to the sleeve conductor, relay 813 is placed in series with it. The action of relay 813 closes the circuit of relay 25 803, which, when acting in turn, completes the circuit of relay 821 by the following path: ground, back contacts of relay 812, 841, contacts of relay 803, winding of relay 821 to battery B. As soon as relay 821 operates, its circuit is maintained locked to ground through the back contacts of relay 30 812. The operation of relay 821 opens one path by which the winding of relay 813 is connected to the sleeve conductor 831. The operation of relay 813 also completes the circuit of the test relay 814 by the following path: ground, contacts of relay 813, 849, contacts of relay 822, 850, cam springs 861, 40 851, winding of relay 814 to battery B. The operation of relay 813 also removes ground from the locking contact of relay 802 which upon falling back closes a path from the winding of relay 812 to the tip conductor 45 830. The operation of relay 814 closes the circuit of the vertical magnet 809 by the following path: ground, back contacts of relay 817, 854, contacts of relay 814, 855, winding of the magnet 809 to battery B.

50 The operation of relay 814 also completes the circuit of relay 816 which in turn completes the circuit of relay 815. The operation of this latter relay severs the tip and sleeve trunk conductors. When relay 814 is 55 operated, its circuit is maintained locked to ground through the back contacts of relay 817. At each stroke of the magnet 809, relay 817 is operated and removes ground from the locking contact of relay 814 and 60 also opens the circuit of the magnet 809. As soon as the magnet 809 falls back, the circuit of relay 817 is opened and the circuit of magnet 809 is again closed. This action will continue until the relay 814 becomes deener-

gized, which will be when the test wiper 865 65 engages an idle contact and relay 817 is energized. As soon as an idle trunk is picked out, relay 814 in falling back opens the circuit of relay 816. This latter relay falling back in turn opens the circuit of relay 815. 70 When relay 816 was first operated, it closed the circuit of relay 819 by the following path: ground, contacts of relay 822, 844, contacts of relay 820, 845, contacts of relay 818, 846, contacts of relay 816, 847, 75 winding of relay 819 to battery B. The operation of relay 819 opens one path by which the winding of relay 813 is connected to the sleeve conductor 831, and also opens one path by which the winding of relay 812 is 80 connected to the tip conductor 830. The winding of relay 812 now has only one path to the tip conductor through the back contacts of relay 802 while the winding of relay 813 only has one path to the sleeve conductor through the back contacts of relay 821 and the upper contacts of relay 820, which 85 is energized.

At the first vertical step of the switch E', the cam springs 861 are opened, thereby 90 breaking the circuits of the magnet 808 and the test relay 814. The operation of relay 819 also short circuits the condensers 866 and 867 so as to allow the control relay of the sending device to be placed in series with 95 the stepping relays of the connector switch, Fig. 4^a, over the tip and sleeve conductors.

When an idle connector is picked out, such as shown in Fig. 4^a, it is operated in the same manner as previously described. 100 When the stepping magnet 970, Fig. 4^a, is placed in series with the control relay of the sending device over the tip conductor, relay 812, Fig. 3^a, becomes energized but at once completes the circuit of relay 800, 105 which in turn completes the circuit of relay 802. The action of this latter relay opens the only path by which the winding of relay 812 is then connected to the tip conductor 830. The same effect is produced while the 110 connector is being controlled over the sleeve conductor as relay 813 becomes energized, and completes the circuit of relay 803, which in turn completes the circuit of relay 821, 115 which upon acting opens the only path by which the winding of relay 813 is then connected to the sleeve conductor.

When the final test impulse is transmitted to the connector, the operation of relay 972, Fig. 4^a, completes the circuit of relay 818, 120 Fig. 3^a, by the following path: ground, contacts of relay 972, cam springs 996, 904, wiper 866 of the switch E', winding of relay 818 to battery B. The operation of relay 818 in response to the momentary test impulse opens the circuit of relay 819. This latter relay falling back removes the short circuits from the condensers 866 and 867. 125

These condensers, being reinserted in the tip and sleeve conductors respectively, prevent battery current from the connector flowing back over the tip and sleeve conductors to the originating exchange.

The talking circuit of the calling and called subscribers passes through the tip and sleeve conductors, Fig. 3^a, indicated by the heavy lines.

- 10 At the termination of the conversation, the called subscriber releases the connector, Fig. 4^a, in the usual manner. The calling subscriber upon hanging up his receiver, restores the first selector switch D in the regular manner. This switch in the act of restoring closes the circuit of relay 811, Fig. 3^a, by the following path: ground, cam springs 128 of the switch D, 145, locking contacts of relay 115, 137, contacts of relay 20 117, 136, contacts of relay 109, 135, wiper 143, 833 winding of relay 811 to battery B. The operation of relay 811 completes the circuit of relay 810 from battery through the resistance coil 834. The winding of this 25 coil is of a high resistance as compared to the winding of relay 810. The operation of these two relays 810 and 811 closes the circuits of relays 812 and 813; the former by the following path: ground, contacts of relay 30 811, contacts of relay 810, tip conductor 830, winding of relay 812, by either of the two paths previously traced to battery B. The circuit of the latter relay 813 is closed by the following path: ground, winding of 35 relay 810, locking contacts of relay 810, sleeve conductor 831 to the winding of relay 813, by either of the two paths formerly traced, to battery B. The operation of relay 812 completes the circuit of relay 800 and 40 the operation of relay 813 completes the circuit of relay 803. The operation of relays 803 and 800 at the same instant closes the circuit of relay 822 by the following path: ground, contacts of relay 803, 859, contacts 45 of relay 800, 860, winding of relay 822, to battery B. The operation of relay 800 is however only momentary as relay 811 after restoring removes ground from the tip conductor 830 and allows relay 812 to fall back. 50 Relay 813, which is connected to the sleeve conductor 831 remains locked in series with the winding of relay 810 through the locking contacts of this latter relay. The operation of relay 813 maintains the circuit of 55 relay 803 closed. The operation of this latter relay maintains the circuit of relay 822 locked to ground through its upper contacts. The circuit of the release magnet 872 of the switch E' is closed by the following 60 path: ground, contacts of relay 822, contacts of relay 800, winding of magnet 872 to battery B. The operation of this magnet causes the switch E' to restore. When this switch reaches its normal position, the cam springs

860 are opened thereby releasing the relay 65 820. The releasing of this relay removes the winding of relay 813 from the sleeve conductor 831 thereby breaking the circuits of relays 813 and 810. The former relay falling back releases relay 803 and this latter 70 relay in turn unlocks relay 822 thereby opening the circuit of the release magnet 872. Relay 810 falls back and removes ground from the test contacts 832, so as to enable this particular trunk to be picked out by a 75 first selector switch.

From the foregoing it will be noted that relays 810 and 813 have their windings connected in series until the switch E' finally restores. The operation of relay 810 during 80 this restoring interval renders the test contacts in the first selector switches busy.

In connection with Fig. 3^a, I have shown a resistance coil connected to a contact in relay 812. When relay 812 is energized, battery B is connected to the sleeve conductor 831 through the winding of the resistance coil. The connection is made in this manner so as to charge the conductor 831 to prevent relay 813 from receiving a "kick" when relay 820 becomes energized when it is connected to the sleeve conductor 831 by the action of relay 820. This latter relay is energized when the switch E' rotates and closes the cam springs 860.

While my invention is not limited to any particular grouping relation between primary trunks and intermediate trunks, the preferred arrangement is as follows. Assuming a 5,000 line system organized on a ten per cent. trunking basis, there would be 50 groups of subscribers' lines consisting of 100 lines each. Each such group would be provided with a group of 10 primary trunks. A single group of key sets would be provided consisting of approximately 50 key sets. Interposed between the primary trunks and the key set group would be a group of 50 intermediate or secondary trunks; and these intermediate trunks would be divided 110 into five sub-groups of ten trunks each.

Each sub-group of intermediate trunks would serve 100 primary trunks, and these 100 primary trunks would preferably include a certain number of trunks from each primary group. Thus the first sub-group of intermediate trunks would be arranged to connect to the first two primary trunks of each primary trunk group; the second sub-group to the primary trunks numbered 3 and 4 in each primary group; the third sub-group to the trunks numbered 5 and 6 in each primary group; the fourth sub-group to the trunks numbered 7 and 8 in each primary group; and the last sub-group of intermediate trunks would connect to primary trunks numbered 9 and 10 in each primary group.

By this method of grouping it will be seen that any calling subscriber's line may be extended to the group of key sets by means of any intermediate trunk in the system; and the accidental tie up of a sub-group of intermediate trunks will not prevent any group of subscribers' lines from being extended to the group of key sets.

Whereas, in the following claims the terms "tens relays" and "units relays" are used, it is to be understood that these terms are not used in a restricted sense. The former term is intended to define those relays which serve to extend the multiple connections of a sub-group of subscribers' lines, and the latter term is used as defining those relays which serve to extend the multiple connections of a single line, in the process of so-called "relay selection."

Having thus described my invention, what I desire to secure by Letters Patent is:

1. In a telephone exchange system, the combination with telephone lines, of trunk lines, a group of tens and units-relays for connecting said lines to said trunk lines, starting conductors for said tens and units-relays, and controlling means comprising a related group of auxiliary-relays for preventing the operation of more than one tens-relay and one units-relay in said group over said starting conductors, substantially as set forth.

2. In a telephone exchange system, the combination with telephone lines, of means associated with the lines for initiating a call, a group of tens and units-relays for said lines, and means comprising a group of related control relays for preventing the action of more than one tens-relay and one units-relay in the group when a plurality of calls are initiated, substantially as set forth.

3. In a telephone exchange system, the combination with telephone lines, of trunk lines, a set of relays each containing terminals of a plurality of said telephone lines, a set of stub trunk conductors connected in multiple to corresponding terminals in all of said relays, a second set of relays each controlling one only of a set of stub-trunk conductors, starting circuits individual to each relay of the two sets and means comprising a group of related control relays for energizing one relay only of the first set and one relay only of the second set over said starting conductors, substantially as set forth.

4. In a telephone exchange system, the combination with a plurality of subscribers' lines arranged in groups, of a group of tens and units-relays associated with said lines, a tens-starting conductor common to each group of lines, units-starting conductors individual to each line, an auxiliary set of relays, each one being individual to a group of lines, and means whereby when an auxiliary relay is actuated the units-starting conduc-

tors of a group of lines are connected to a set of units-relays, substantially as set forth.

5. In a telephone exchange system, the combination with a plurality of subscribers' lines arranged in groups, of a group of tens and units-relays associated with said lines, a tens-starting conductor common to each group of lines, units-starting conductors each one being individual to a line, an auxiliary set of relays each one being individual to a group of lines, and means whereby when a plurality of auxiliary relays are actuated only one of the set is rendered effective to connect the tens and units-starting conductors of its group to the set of tens and units-relays, substantially as set forth.

6. In a telephone exchange system, the combination with a plurality of subscribers' lines arranged in groups, of a group of tens and units-relays associated with said lines, a tens-starting conductor common to each group of lines, units-starting conductors individual to each line, an auxiliary relay individual to each tens starting wire, and means whereby in case of simultaneous calls the action of only one auxiliary relay is rendered effective to extend the starting circuits to the tens and units relays, substantially as set forth.

7. In a telephone exchange system, the combination with a plurality of subscribers' lines arranged in groups, of a group of tens and units-relays associated with said lines, a tens-starting conductor common to each group of lines, units-starting conductors individual to each line, a set of auxiliary relays, and means whereby in case a plurality of auxiliary relays are actuated only one is rendered effective to extend connection to a tens-relay of the set, substantially as set forth.

8. In a telephone exchange system, the combination with a plurality of subscribers' lines arranged in groups, of a group of tens and units-relays associated with said lines, a tens-starting conductor common to each group of lines, a units-starting conductor individual to each line, a serially related group of auxiliary relays, each one being individual to a tens-starting conductor, and means whereby in case of simultaneous calls only one auxiliary relay is rendered effective to extend connection to a tens-relay and a units-relay of the group, substantially as set forth.

9. In a telephone exchange system, the combination with a plurality of subscribers' lines arranged in groups, of a group of tens and units-relays associated with said lines, a control conductor to each group of lines, a control conductor individual to each line, an auxiliary set of relays, each one being individual to a common control conductor and means whereby in case of simultaneous calls one only of the auxiliary relays is rendered effective to extend control to the tens and

units-relays and only one tens-relay and one units-relay of the set is energized, substantially as set forth.

10. In a telephone exchange system, the combination with a plurality of subscribers' lines arranged in groups, of a group of tens and units-relays associated with said lines, a control conductor common to each group of lines, a control conductor individual to each line, an auxiliary set of relays, a master-relay common to the group of auxiliary relays and means whereby upon the actuation of an auxiliary relay of the set the master-relay is operated to disable the common control wires, substantially as set forth.

11. In a telephone exchange system, the combination with a plurality of subscribers' lines arranged in groups, of a group of tens and units-relays associated with said lines, a tens-starting conductor to each group of lines, units-starting conductors individual to each line, a set of auxiliary relays each one being individual to a tens-starting conductor, a master relay common to the set of auxiliary relays, and means whereby in case any auxiliary relay is operated the master-relay is actuated to prevent the operation of other auxiliary relays over said tens starting wires, substantially as set forth.

12. In a telephone exchange system, the combination with a plurality of subscribers' lines arranged in groups, of a group of tens and units relays associated with said lines, an auxiliary set of relays for controlling the action of the group of tens and units-relays, a master-relay common to a group of auxiliary relays, signaling means associated with the master relay and additional means for rendering the same operative in case said relay remains operated for an abnormal period, substantially as set forth.

13. In a telephone exchange system, the combination with a plurality of electrical circuits arranged in groups, of a group of tens and units-relays associated with said circuits, a tens starting conductor common to the group of circuits, units-starting conductors individual to each circuit, an auxiliary set of relays each one being individual to a group of said circuits, and means whereby when an auxiliary relay is actuated the units-starting conductors of a group of electrical circuits are extended to the set of units-relays, substantially as set forth.

14. In a telephone exchange system, the combination with a plurality of electrical circuits, a group of tens and units-relays for said circuits, means comprising a group of control relays for preventing the action of but one tens relay and one units relay in the group when a plurality of electrical circuits are energized, substantially as set forth.

15. In a telephone exchange system, the combination with a plurality of subscribers' lines arranged in groups, of a group of tens

and units relays associated with said lines, a tens starting conductor common to each group of lines, units-starting conductors individual to each line, an auxiliary set of relays each one being individual to a group of lines, controlling means for said auxiliary set of relays whereby their order of precedence in extending connections to the tens and units relays is changed, substantially as set forth.

16. In a telephone exchange system, the combination with a group of electrical circuits, a group of auxiliary circuits, of controlling means for said auxiliary circuits normally inactive, an alarm signal associated with said controlling means, and additional means for rendering the controlling means active and operating the alarm signal after a delayed period, substantially as set forth.

17. In a telephone exchange system, the combination with a plurality of subscribers' lines arranged in groups, of a group of tens and units-relays associated with said lines, an auxiliary set of relays for controlling the group of tens and units-relays, and controlling means associated with the set of auxiliary relays serving to change the order of precedence in which the auxiliary relays are rendered effective to control the tens and units relays of the group associated with said lines, substantially as set forth.

18. In a telephone exchange system, the combination with a plurality of subscribers' lines arranged in groups, of a group of tens and units-relays associated with said lines, an auxiliary set of relays for controlling the group of tens and units-relays, and a step-by-step switch associated with the set of auxiliary relays and serving to change the order of precedence in which the auxiliary relays are rendered effective to control the tens and units-relays associated with said lines, substantially as set forth.

19. In a telephone exchange system, the combination with a plurality of telephone lines, of trunk lines, a group of tens and units-relays for interconnecting said telephone lines and trunk lines, and controlling means associated with said group of tens and units-relays for changing the order of precedence in which said telephone lines are connected to said trunk lines, substantially as set forth.

20. In a telephone exchange system, the combination with a plurality of telephone lines arranged in groups, of a group of tens and units relays associated with said lines, energizing circuits for each tens and units-relay of the group, and controlling means whereby the order of precedence in which said energizing circuits are rendered effective is changed, substantially as set forth.

21. In a telephone exchange system, the combination with a plurality of electrical

circuits, and controlling means for said electrical circuits for changing the order of precedence in which said electrical circuits are rendered effective, substantially as set forth.

22. In a telephone exchange system, the combination with a group of telephone lines, of trunk lines, a group of tens and units-relays for interconnecting said telephone lines and said trunk lines, and controlling means for changing the order of precedence in which said tens and units-relays are operated and in which said telephone lines are connected to said trunk lines, substantially as set forth.

23. In a telephone exchange system, the combination with a plurality of telephone lines, of a trunk line, of a group of tens and units relays for interconnecting said telephone lines with said trunk line, a set of auxiliary relays associated with said telephone lines, and means whereby upon the initiation of a plurality of calls over said telephone lines, said auxiliary relays are rendered effective to actuate but one tens-relay and one units-relay of the group whereby but one telephone line is connected to said trunk line, substantially as set forth.

24. In a telephone exchange system, the combination with a plurality of subscribers' lines of a group of primary trunks associated with said lines, a series starting conductor for said group of primary trunks over which an idle one of said primary trunks is selected, means rendered operable during the selection to prevent another idle trunk in the group being selected, substantially as set forth.

25. In a telephone exchange system, the combination with a plurality of subscribers' lines, of a group of primary trunks associated with said lines, a series starting conductor for said group of primary trunks over which an idle one of said primary trunks is selected, a slow relay associated with each primary trunk, of means for rendering said relay operative during the selection of its associated trunk to open the starting conductor leading to another idle trunk, substantially as set forth.

26. In a telephone exchange system, the combination with a calling telephone line, of a trunk line, and means for interconnecting said telephone line with said trunk line, a selector switch associated with said trunk line, and through which the initial action of the interconnecting means is controlled, releasing means for said selector switch, additional means associated with said trunk line for delaying the action of the releasing means for said selector switch, substantially as set forth.

27. In a telephone exchange system, the combination with a calling telephone line, of a trunk line, means for interconnecting

said telephone line and said trunk line, a selector switch associated with said trunk line and through which the initial action of the interconnecting means is controlled, releasing means for said selector switch, a slow relay associated with said trunk line, said relay serving to delay the operation of the releasing means of the selector switch, substantially as set forth.

28. In a telephone exchange system, the combination with calling telephone lines of trunk lines, means for connecting said telephone lines with said trunk lines including a device capable of changing the order of the precedence in which said telephone lines are connected with said trunk lines, releasing means for the connecting means, a slow relay associated with said trunk lines, said relay serving to delay the action of the releasing means, substantially as set forth.

29. In a telephone exchange system, the combination with a calling subscriber's line, a called subscriber's line, of automatic switching mechanism for interconnecting the lines, including a trunk selector switch and means for selecting a trunk selector, a trunk line comprising but two conductors arranged to connect the trunk selector to its selecting means and over which the action of the trunk selector is controlled, means for restoring the switches, comprising means for guarding against the action of the selecting means, said guarding means being connected at restoration of the means for selecting the trunk selector and controlled by the trunk selector switch, substantially as set forth.

30. In a telephone exchange system, the combination with calling and called subscribers' lines, mechanism for interconnecting the lines, including automatic selector and trunk selector switches and a two conductor trunk line between the two sets of said switches, and means for restoring the switches, including mechanism for preventing the selection of the trunk line until after the restoration of the trunk selector switch, the mechanism for preventing the selection of the trunk being connected at restoration of said automatic selector and controlled by the trunk selector switch, substantially as set forth.

31. In a telephone exchange system, the combination with calling and called subscribers' lines, means for interconnecting the lines, including first selector, trunk selector and connector switches, said trunk selector switches being provided with special wipers engaging special contacts associated with the connector switches, and means including an impulse controlling device for directing the operation of the switches, a special trunk line composed of only two conductors extending between the first selector and trunk selector switches and

- over which the impulses are controlled to operate the trunk selector and connector switches, condensers normally in series with lines leading to said trunk selectors and 5 means responsive to impulses over the special trunk line for operating the trunk selector and for short circuiting the condensers so that the impulses may direct the operation of the connector switch, and 10 means responsive to the last test impulse for reinserting the condensers in circuit, said means being controlled through the special wiper of the trunk selector switch, substantially as set forth.
- 15 32. In a telephone exchange system, the combination with a calling subscriber's line, a called subscriber's line, means for interconnecting the lines, including first selector, second or trunk selector and connector 20 switches, said second or trunk selector switch being provided with a special wiper, and means including an impulse controlling device for directing the operation of the switches, a two-conductor trunk extending 25 between the first selector and the trunk selector switches, over which the impulses are controlled for operating the trunk selector and connector switches, and controlling means in said trunk selector, said controlling means rendered operable over said 30 special wiper in response to the last test impulse of the connector switch, substantially as set forth.
33. In a telephone exchange system, the combination with a two-conductor trunk, of a stepping or repeating relay normally connected to one conductor of said trunk and a second stepping or repeating relay associated with but normally disconnected 35 40 from the second of said trunk conductors, and means for connecting the second relay to said second-trunk conductor, additional means controlled by the first relay for charging the second-trunk conductor to prevent 45 premature action of the second relay when said connecting means is operated, substantially as set forth.
34. In a telephone exchange system, the combination with a two-conductor trunk, 50 of a relay normally connected to one of said conductors and a second relay associated with but normally disconnected from the second trunk conductor, and means for connecting the second relay to the second trunk 55 conductor, additional means controlled by the first relay to charge said second-trunk conductor to prevent a "flipping" of the second relay when said connecting means is operated, substantially as set forth.
- 60 35. In a telephone exchange system, the combination with a first selector switch, of a repeating relay and a test-relay associated with said switch, a control relay also associated with said switch, a control circuit 65 for said switch, and means whereby the control relay is operated to connect the repeating relay and test relay with said control circuit, substantially as set forth.
36. In a telephone exchange system, the combination with a plurality of telephone 70 lines arranged in groups, of trunk lines, a group of tens and units-relays for interconnecting said telephone lines and said trunk lines, a group of auxiliary relays provided with contacts through which the 75 tens and units relays are operated, controlling means associated with said group of auxiliary relays for changing the order of precedence in which said groups of telephone lines are connected to said trunk 80 lines, said controlling means also serving to prevent tying up all of the groups of telephone lines in case of an open contact in said auxiliary group of relays, substantially as set forth.
- 85 37. In a telephone exchange system, the combination with a plurality of telephone lines, of trunk lines, and means for connecting said trunk lines with said telephone lines, starting conductors for said trunk 90 lines, a step-by-step switch controlling said trunk lines, whereby the order of precedence in which said trunk lines are connected to said telephone lines is changed, said step-by-step switch also serving to prevent tying up of a group of trunks in case of an open starting conductor, substantially as set forth.
- 95 38. In a telephone exchange system, the combination with a plurality of trunk lines, starting conductors over which said trunk lines are placed in service, a step-by-step switch for controlling said trunk lines whereby the order in which said trunk lines are placed in service is changed, said step-by-step switch also serving to prevent tying up of a group of trunks in case of an open starting conductor, substantially as set forth.
- 100 39. In a telephone exchange system, the combination with plurality of telephone lines arranged in groups, of trunk lines, a group of tens and units relays for interconnecting said telephone lines and trunk lines, starting conductors for said tens and units-relays and also starting conductors for said trunk lines, a step-by-step switch for controlling the order of precedence in which the groups of telephone lines and trunk lines are connected, said step-by-step 11 switch also serving to prevent tying up all of the groups of telephone lines or trunk lines in case of an open in said starting conductors, substantially as set forth.
- 110 40. In a telephone exchange system, the combination with a calling subscriber's line, a primary trunk adapted to automatically select a line on initiation of a call, a tertiary trunk containing a key-board and control device, a secondary trunk interposed 115

between said primary trunk and tertiary trunk, means controlled by said calling line to cause the secondary trunk to select said primary trunk and the tertiary trunk to select said secondary trunk, said selection of the tertiary trunk being exercised over three conductors extending from said secondary trunk, substantially as set forth.

41. In a telephone exchange system, the combination with a telephone line, a primary trunk for selecting said line, a secondary trunk for selecting said primary trunk, a tertiary trunk for selecting said secondary trunk, the selection of the secondary trunk by the tertiary trunk being controlled over but three conductors extending from said secondary trunk, substantially as set forth.

42. In a telephone exchange system, the combination with a plurality of groups of primary trunks, of a single group of key-sets, said key-sets being associated with a plurality of groups of intermediate trunks, each group of intermediate trunks being directly associated with groups of primary trunks, and means to connect any trunk of a group of intermediate trunks with primary trunks of any of said groups of primary trunks, and additional means to connect any one of said single group of key-sets with any intermediate trunk of said plurality of groups of intermediate trunks.

43. In a telephone exchange system, the combination with a plurality of groups of primary trunks, of a single group of key-sets, a plurality of groups of intermediate trunks with which said key sets are associated, each group of intermediate trunks being directly associated with a plurality of groups of primary trunks, and means whereby each group of intermediate trunks can select a plurality of groups of primary trunks, and additional means whereby said single group of key-sets can select a plurality of groups of intermediate trunks, substantially as set forth.

44. In a telephone exchange system, the combination with a plurality of groups of primary trunks, of a plurality of key sets, and means comprising groups of intermediate trunks whereby any primary trunk in the said plurality of groups can become associated with any one of a plurality of said key sets, said means comprising groups of tens and units relays provided with associated groups of controlling relays, substantially as set forth.

45. In a telephone exchange system, the combination with a plurality of calling subscribers' lines, of a plurality of groups of primary trunks, a group of tertiary trunks and associated key-sets, and means for connecting the primary trunks with said subscribers' lines, means comprising a plurality of groups of secondary trunks interposed

between said primary and tertiary trunks whereby any one of the plurality of calling subscribers' lines can become associated with the first idle key-set of said group, substantially as set forth.

46. In a telephone exchange system, the combination with a plurality of groups of primary trunks, of a single group of key-sets, said key-sets being associated with a plurality of groups of intermediate trunks, each group of intermediate trunks being associated with a plurality of groups of primary trunks, and selective means comprising sets of tens and units relays whereby each group of intermediate trunks can select a plurality of groups of primary trunks, and additional selective means comprising sets of tens and units relays whereby said single group of key-sets can select a plurality of groups of intermediate trunks, substantially as set forth.

47. In a telephone exchange system, the combination with a group of primary trunks, of a group of key sets, intermediate trunks interposed between said primary trunks and key sets, selective means comprising a set of tens and units-relays whereby a primary trunk is extended to an intermediate trunk, additional selective means comprising a set of tens and units-relays whereby said intermediate trunk is extended to a key set of the group, controlling means for each of said selective means whereby each step in the order of said selection is completed before another selection is started, substantially as set forth.

48. In a telephone exchange system, the combination with a plurality of calling subscribers' lines, a plurality of key sets, means comprising primary, secondary and tertiary sets of relays whereby any calling subscriber's line is connected to the first idle one of said key sets, means comprising sets of relays for controlling said connection by said tens and units-relays, substantially as set forth.

49. In a telephone exchange system, the combination with a plurality of calling subscribers' lines, of a plurality of key sets, means comprising primary, secondary and tertiary selections whereby any calling subscriber's line is connected to the first idle one of said key sets, said selections being accomplished by means of groups of tens and units-relays, controlling means for said tens and units-relays comprising groups of corresponding sets of master relays, substantially as set forth.

50. In a telephone exchange system, the combination with a plurality of secondary trunks, of a group of tertiary or key-set trunks, and connecting means for said tertiary and secondary trunks, a starting conductor for said tertiary trunks over which an idle one of said tertiary trunks is se-

- lected, controlling means comprising a step-by-step switch for said tertiary trunks, means in case of a failure in said connecting means by reason of a break in said starting conductor, the said step-by-step switch will be caused to step past such break, substantially as set forth. 5
51. In a telephone exchange system, the combination with a group of tertiary or key-set trunks, said trunks being provided with selective apparatus, a starting conductor for said trunks over which an idle one of said trunks is selected, a step-by-step switch associated with said trunks, and 10 means whereby in case of a failure in the selective apparatus of a tertiary trunk by reason of a break in said starting conductor the step-by-step switch will start and step past such break, substantially as set forth. 15
52. In a telephone exchange system, the combination with a plurality of secondary trunks, of a group of tertiary or key set trunks, connecting means for said tertiary and secondary trunks, a starting conductor 20 for said tertiary trunks over which an idle one of said tertiary trunks is selected, a controlling device for said tertiary trunks, means in case of a failure in said connecting means by reason of a break in said starting conductor to cause said controlling device to bridge over such break, substantially as 25 set forth. 30
53. In a telephone exchange system, the combination with a plurality of secondary trunks, of a group of tertiary or key-set trunks, connecting means for said tertiary and secondary trunks, a starting conductor over which an idle one of said tertiary trunks is selected, a control device for said 35 tertiary trunks, means in case of a break in said starting conductor to cause said controlling device to bridge over such break and display an alarm signal, substantially as set forth. 40
54. In a telephone exchange system, the combination with a plurality of groups of primary trunks, of a single group of key sets, said key sets being associated with a 45 plurality of groups of intermediate trunks, and each group of intermediate trunks being associated with a plurality of primary trunks in each group of primary trunks. 50
55. In a telephone exchange system, the combination with a plurality of groups of primary trunks, of a single group of key sets, said key sets being associated with a 55 plurality of groups of intermediate trunks, and each group of intermediate trunks being directly associated with one or more primary trunks in each group of primary trunks. 60
56. In a telephone exchange system, the combination with a plurality of groups of primary trunks, of a single group of key sets, said key sets being associated with a 65

70 plurality of groups of intermediate trunks, and one or more primary trunks in each group of primary trunks being directly associated with each group of intermediate trunks.

75 57. In a telephone exchange system, the combination with a plurality of groups of subscribers' lines, of a group of primary trunks for each group of subscribers' lines, a single group of key sets, a group of intermediate trunks, and means whereby any calling subscriber's line may be extended to the group of key sets by means of a primary trunk and any one of said intermediate trunks. 80

85 58. In a telephone exchange system, the combination with telephone lines, of a line relay individual to each of said lines, means associated with the lines for operating their respective line relays, a group of tens and units relays for said lines, means for operating said tens and units relays in response to the operation of said line relays, additional means for preventing the action of more than one tens relay and one units relay in the group when a plurality of line relays are operated, substantially as set forth. 90

95 59. In a telephone exchange system, the combination with a plurality of telephone lines having individual line relays, means associated with the lines for operating said line relays upon the initiation of calls, a group of tens and units relays for said lines, and means comprising a group of control relays for preventing the action of more than one tens relay and one units relay in the group when a plurality of calls are initiated, substantially as set forth. 100

105 60. In a telephone exchange system, the combination with a plurality of telephone lines having individual line relays, of means for operating said relays, a group of tens and units relays for said lines, means responsive to the operation of said line relays to prevent the action of more than one tens relay and one units relay in the group when a plurality of line relays are operated, substantially as set forth. 110

115 61. In a telephone exchange system, the combination with a plurality of telephone lines, a group of tens and units relays for said lines, means individual to each of said lines for operating said tens and units relays, additional means for preventing the action of more than one tens relay and one units relay in the group when a plurality of calls are initiated over said lines, substantially as set forth. 120

125 62. In a telephone exchange system, the combination with a plurality of subscribers' lines arranged in groups, of a group of tens and units relays associated with said lines, a tens-starting conductor common to each group of lines, units-starting conductors individual to each line, an auxiliary device in- 130

dividual to each tens-starting wire, and means whereby in case of simultaneous calls the action of only one auxiliary device is rendered effective to extend said starting conductors to the tens and units relays, substantially as set forth.

63. In a telephone exchange system, the combination with a plurality of subscribers' lines arranged in groups, of a group of tens and units relays associated with said lines, a set of auxiliary relays, means whereby in case a plurality of auxiliary relays are actuated only one is rendered effective to extend connection to a tens and units relay of the group, substantially as set forth.

64. In a telephone exchange system, the combination with a plurality of subscribers' lines, of a group of tens and units relays associated with said lines, a set of auxiliary devices, and means whereby in case a plurality of said devices are operated only one is rendered effective to extend the connection to a tens relay and a units relay of the group, substantially as set forth.

65. In a telephone exchange system, the combination with a plurality of electrical circuits, a group of tens and units relays for said circuits, a set of control devices, means for operating said control devices when said electrical circuits are energized, additional means whereby in case of a plurality of simultaneous energizations of said electrical circuits but one of said devices is rendered effective to cause the action of tens and units relays, substantially as set forth.

66. In a telephone exchange system, the combination with a plurality of telephone lines, of a trunk line, a group of tens and units relays for interconnecting said telephone lines with said trunk line, a set of auxiliary devices associated with said telephone lines, and means whereby upon the initiation of a plurality of simultaneous calls over said telephone lines but one auxiliary device is rendered effective to cause the actuation of but one tens relay and one units relay of the group whereby but one of said telephone lines is connected to said trunk line, substantially as set forth.

67. In a telephone exchange system, the

combination with a plurality of trunk lines, means for placing said trunk lines in service, a step-by-step switch for controlling the order in which said trunk lines are placed in service, said step-by-step switch also serving to prevent tying up of a group of trunks in case of a failure to place a trunk line in service, substantially as set forth.

68. In a telephone exchange system, the combination with a plurality of trunk lines, starting conductors over which said trunk lines are placed in service, means for controlling said trunk lines whereby the order in which they are placed in service is changed, said controlling means also serving to prevent tying up of a group of trunks in case of an open starting conductor, substantially as set forth.

69. In a telephone exchange system, the combination with a plurality of telephone lines arranged in groups, of trunk lines, a group of tens and units relays for interconnecting said telephone lines and trunk lines, starting conductors for said tens and units relays and also starting conductors for said trunk lines, means controlling the order of precedence in which the group of telephone lines and trunk lines are interconnected, said controlling means also serving to prevent tying up of the groups of telephone lines or trunk lines in case of an open in said starting conductors, substantially as set forth.

70. In a telephone exchange system, the combination with a plurality of subscribers' lines, of a group of tens and units relays associated with said lines, an auxiliary device for controlling the action of the tens and units relays of said group, a master relay common to said auxiliary device, signaling means associated with the master relay, and additional means for rendering the signaling means operable in case said master relay remains operative for an abnormal period, substantially as set forth.

In witness whereof, I hereunto subscribe my name this 4th day of Mch, A. D. 1913.

HARRY G. WEBSTER.
